LASTING MACHINE

Robert H. Lawson, Beverly, Mass., assignor to
 United Shoe Machinery Corporation, Paterson,
 N. J., a corporation of New Jersey

Application March 25, 1932, Serial No. 601,082

104 Claims. (Cl. 12—4)

This invention relates to machines for use in the manufacture of shoes and is illustrated herein as embodied in a lasting machine.

In lasting the sides of Goodyear welt shoes the upper is ordinarily stretched over the last and then wiped inwardly over the margin or feather or the insole and into engagement with a lip or rib of the insole to which it is permanently secured in lasted relation by fastenings. These fastenings, which in present-day practice are usually staples, are inserted through the marginal portion of the upper and the lip or rib of the insole and are clenched against an anvil which backs up the rib of the insole. The side lasting operation precedes the inseaming or welt attaching operation and the fastenings are intended to hold the upper against displacement from properly lasted position until the inseaming operation is completed.

20 While the staples are inserted with great accuracy and in such locations that the overlaid portions of the shoe upper are held flat upon the feather of the insole in a most satisfactory manner, it has been found that under certain conditions the lip or rib of the insole sometimes yields and becomes displaced because of an excessive pull on the rib transmitted by the staples. Any displacement of the rib of the insole is undesirable since it permits the upper to become slack on the last and, moreover, tends to prevent the forming of a tight inseam in the subsequent welt attaching operation.

It is, accordingly, an object of the present invention to provide an improved side lasting machine arranged to work a shoe upper into lasted relation to a last and insole and to secure the shoe upper permanently in lasted relation to the insole by one set of fastenings and temporarily to the last by another set of fastenings which serve as additional holding means to prevent displacement of the rib and the shoe upper and which may be removed after the upper has set and before the subsequent inseaming operation is performed.

The illustrated machine is of the same general type as the machine disclosed and claimed in Letters Patent of the United States No. 1,854,204, granted April 19, 1932, on an application of mine, although it will be recognized that in many novel and useful aspects the invention is not limited to machines of the particular type illustrated.

The illustrated machine, like the machine of the prior Letters Patent above mentioned, is arranged to last the sides of the shoe progressively by working the opposite marginal portion of the shoe upper along the sides inwardly transversely

of the insole and fastening it in lasted relation to the insole. The machine is provided with a jack arranged to support a last having a shoe upper and a ribbed insole positioned thereon and with a pair of lasting units located one upon each side of the shoe to be operated upon. By relative movement of the units and the jack the lasting operation is performed progressively from the heel-breast line forwardly to the tip line at the toe end of the shoe.

65 The lasting units of the illustrated machine are provided with grippers for tensioning the shoe upper over the last and an important feature of the invention resides in a novel organization of overwiping means and fastening inserting 70 means affording provision for the fastening of the opposite marginal portions of the shoe upper by a plurality of separate fastenings of different kinds while the wiping means are maintained at the limit of their overwiping movement. In 75 its embodiment of this feature of the invention the construction herein shown comprises wipers carried by slides movable toward and from the work and provided with staple guiding nozzles through which staples are driven to secure the 80 upper permanently in lasted relation to the insole, and separate slides movable toward and from the work in response to movement of the wiper carrying slides and provided with nozzles through which tacks are driven to secure the upper 85 temporarily in lasted relation to the last. Since the illustrated machine is intended to be used for lasting Goodyear welt shoes, it is arranged to insert the staples through the shoe upper and the rib of the insole and to clench 90 the staples on anvils which back up the rib of the insole and to insert the tacks through the upper, in the angle between the rib and the feather of the insole, into the insole and last close to the base of the rib. In order to determine with accuracy the location of the tacks with respect to the rib of the insole, one of said slides is provided also with a nose portion having a 95 guide-way formed therein for the tacks extending in the direction of tack insertion, said nose portion having a work-engaging face formed and arranged to bend the upper and the rib of the insole inwardly at an angle to the plane of the insole at the point of tack insertion to facilitate the insertion of the tacks close to the base of 100 the rib. Conveniently also this nose portion is provided with a deflecting surface for engaging the tacks during the tack driving operation to deflect them in curved paths inwardly away from the edge of the last bottom to prevent chipping 105 110

of the edge of the last bottom. Thus the opposite overlaid portions of the upper are secured permanently in lasted relation to the insole by staples and temporarily in lasted relation to the last by tacks which may be only partially inserted so that they can be conveniently removed after the upper has set and before the inseaming operation is performed.

In lasting the sides of shoes the uppers of which are scant it is customary with some manufacturers to give certain portions of the upper at opposite sides of the shoe a preliminary pull by hand and then to secure these portions to the insole and last by temporary lasting tacks before the shoe is lasted by machine.

In the illustrated machine the operating means for the grippers is arranged cyclically to impart a heightwise movement to the grippers, through yielding connections, to tension portions of the shoe upper about the last at opposite sides of the shoe and then to lower the grippers into position for gripping successive portions of the shoe upper after the tensioned portions of the upper have been secured in lasted position by fastenings and before the shoe is fed. By the jack movement the shoe is fed step-by-step rearwardly between successive upper tensioning and fastening inserting operations, and in order that the grippers, which are set low enough to grip a scant upper, will not engage previously inserted tacks and interfere with the feeding movements of the shoe the grippers of the illustrated machine are, in accordance with a feature of the invention, held out of the way of such tacks during movement of the shoe to bring previously tensioned portions of the upper into position to be fastened. In the illustrated machine this is effected by the provision of means operating in timed relation to the feeding movements of the jack for rendering the gripper operating mechanism inoperative to lower the grippers while previously tensioned portions of the upper are being secured by the securing means. Also in the illustrated machine, provision is made for automatically rendering the grippers again operative to tension the upper after a predetermined number of operations of the securing means.

It is desirable also, particularly when operating on scant uppers, that sufficient heightwise movement be imparted to the grippers to permit them to swing in their appointed paths without damaging the rib of the insole or interfering with the inward movement of the wipers. Accordingly, another feature of the invention consists in novel means for operating and controlling the grippers arranged to maintain the limit of movement of the grippers away from the insole and shoe upper at a greater height than that of the top of the rib of the insole regardless of the point relatively to the insole at which the grippers engage the shoe upper. In the illustrated machine the heightwise pull of the grippers is varied upon different parts of the shoe upper in order properly to tension the shoe upper as the lasting operation is performed progressively along the sides of the shoe, and the novel gripper operating and controlling mechanism includes a pair of springs operating alternately to vary the stretching force applied to different portions of the upper by the grippers, means being provided, operative upon distortion of the springs, to cause a portion of the pull to be positively effected to increase the movement of the grippers away from the insole if the extent of their impositive move-

ment is insufficient to carry them above the top of the rib of the insole.

The staple forming an inserting mechanism and tack driving mechanism of the illustrated machine are not claimed herein since they form the subject-matter of a copending application Serial No. 673,334, filed May 29, 1933, in the name of Robert H. Lawson.

With the above and other objects and features in view, the invention will now be described with reference to the accompanying drawings which illustrate a preferred embodiment of the invention and will be pointed out in the claims.

Fig. 23 is a plan view and Fig. 24 is a perspective view illustrating a Goodyear welt shoe which has been side lasted by the machine; and

Fig. 25 is a large scale view illustrating the 10 clenching of a staple.

General organization

The illustrated side lasting machine is provided with a box-like base or frame 50 best shown 15 in Figs. 1, 2 and 3 carrying a head 52 which supports at the front of the machine a pair of lasting units 54, 56, each provided with means for working a shoe upper into lasted relation to a last and insole comprising a pair of upper tensioning 20 grippers arranged to grip the opposite marginal portions of the upper to tension the upper height-wise of the last and wipers arranged to wipe the tensioned upper at opposite sides of the shoe simultaneously inwardly over the bottom of the 25 shoe and with staple forming and inserting mechanism and tack driving mechanism arranged to insert staples and tacks substantially simultaneously through the opposite marginal portions of the tensioned shoe upper into the 30 insole and the last to secure the upper permanently in lasted relation to the insole and temporarily in lasted relation to the last. These mechanisms are, for convenience, spoken of in 35 this specification as upper tensioning and fastening inserting units. Beneath these upper tensioning and fastening inserting units is a jack 58 connected by a universal joint to a jack support mounted for movement in a direction substantially perpendicular to the bottom of the shoe 40 and supported by a carrier mounted for movement in a direction extending longitudinally of the shoe to present different parts of the shoe to be operated on successively to the upper tensioning and fastening inserting units 54, 56. The 45 upper tensioning and fastening inserting units 54, 56, are carried by two supports and are provided with presser feet 74, 76 arranged to bear against the inner surface of the rib of the insole at opposite sides of the shoe. The supports are pivotally mounted in the head 52 of the machine and are interconnected so that they move simultaneously 50 toward and from each other. A spring tends to separate the supports and to cause the presser feet to remain in contact with the inner surface 55 of the rib of the insole throughout the lasting and fastening inserting operation on the shoe, and since the supports are interconnected the presser feet serve also to determine the lateral position of the shoe in the machine. The supports are also mounted so that they can be rotated about axes extending approximately at 60 right angles to the surface of the insole of the shoe operated upon and automatic mechanism is provided operating in timed relation with the longitudinal movements of the shoe for rotating the supports to maintain the shoe upper engaging surfaces of the grippers substantially parallel to the portion of the shoe upper being operated upon and to cause the overlaying and securing means to operate in paths substantially normal to the rib of the insole, thus compensating for the edge curvatures of the shoe sole. The presser feet and the supports upon which they are 65 mounted are fixed against vertical movement 70

and in order to maintain the presser feet in contact with the surface of the shoe sole at opposite sides of the shoe throughout the lasting and fastening-inserting operation means is provided operating in timed relation to the travel of the shoe to impart tipping movements to the jack transversely of the direction of feed to maintain the sides of the shoe in proper position to be acted upon by the upper tensioning and fastening-inserting units 54, 56. The jack 58 is yielding urged upwardly to hold a shoe 68 mounted on a last 70 (Fig. 6) carried by the jack 58 in its uppermost position with its innersole 72 pressed against the presser feet or anvils 74, 76 carried by the upper tensioning and fastening-inserting units 54, 56 and means is provided for locking the jack support against downward movement during each operation of the upper tensioning and fastening-inserting units.

When the machine is at rest with the jack in position to permit the removal of a shoe and the placing of another shoe thereon the jack is out of normal operating position in the machine. After a shoe has been placed upon the jack, the operator imparts a slight dipping movement to the jack to unlock the connections through which the jack has been actuated to feed the preceding shoe. The jack is then moved by the operator to bring the shoe to starting position and this movement of the jack adjusts the feeding mechanism in accordance with the size of the shoe to be operated upon. Upon starting the machine the feeding mechanism is locked in adjusted position so that it can function properly to feed the shoe.

The longitudinal movements of the jack to feed the shoe, the tipping movements of the jack to compensate for the longitudinal and transverse curvature of the surface of the sole and the rotary or turning movements imparted to the upper tensioning and fastening-inserting units to compensate for the edge curvature of the shoe sole are produced and controlled by pattern cam mechanism driven in timed relation to the upper tensioning and fastening-inserting units. This pattern cam mechanism is also connected to means for varying the tension of a spring which determines the stretching strain exerted by the lasting grippers on the shoe upper and to mechanism for varying the tension of a spring which tends to separate the supports for the upper tensioning and fastening-inserting units and to hold the presser feet 74, 76 carried by the units 54, 56 in contact with the rib of the insole at opposite sides of the shoe.

The illustrated machine is provided with a driving mechanism from which the upper tensioning and fastening-inserting units and the pattern cam mechanism are driven and is also provided with a stopping mechanism which at the completion of the lasting operation is automatically thrown into operation and which acts to disconnect the upper tensioning and fastening-inserting mechanism and the pattern cam mechanism from the driving mechanism. After the upper tensioning and fastening-inserting mechanisms and the pattern cam mechanism are disconnected from the driving mechanism the jack is depressed and moved outwardly and a final movement is imparted to the pattern cam mechanism to cause the jack to be moved longitudinally in the direction opposite to the feed to its original position. This is accomplished by an auxiliary mechanism normally idle but which is automatically connected to the driving mechanism after

The upper tensioning and fastening-inserting units

the upper tensioning and fastening-inserting mechanisms and the pattern cam mechanism are disconnected.

As previously stated, movement of the shoe into operative position automatically adjusts the feeding mechanism in accordance with the size of the shoe to be operated upon. In order that the operation of the upper tensioning and fastening-inserting units will be started at a predetermined point on the shoe without any special attention on the part of the operator, the jack of the illustrated machine is provided with a gage which when brought into contact with a cooperating gage at the start of the operation on the shoe positions the shoe in the jack in predetermined relation to the operating instrumentalities of the units 54, 56. This cooperating gage is mounted for movement in the machine into and out of operating position. It is moved into operating position during the downward and outward movement of the jack after the lasting operation has been completed and is held in said position by a locking latch which is released upon the starting of the machine to permit the cooperating gage to move into inoperative position. The jack 58 is also connected to mechanism for controlling the positions of the units 54, 56 widthwise of the shoe at the start of the operation on the shoe. This mechanism is controlled by the length of the shoe in the jack through connections which are operative as the jack is moved into operative relation to the units 54, 56 but which are rendered inoperative before the operation upon the shoe is actually started.

The driving and stopping mechanism of the illustrated machine, the mechanism which is thrown into operation when the upper tensioning and fastening-inserting units are thrown out of operation and which depresses the jack and moves it outwardly, the pattern cam mechanism and connections therefrom to the jack for imparting feeding movements to the jack in accordance with the size of the shoe to be operated upon and tipping movements to the jack to compensate for the transverse curvature of the surface of the shoe sole and the connections from the pattern cam mechanism to the means for varying the tension of a spring which determines the stretching strain exerted by the lasting grippers on the upper and to the means for varying the tension of the spring which tends to separate the supports for the upper tensioning and fastening-inserting units and the mechanism for controlling the widthwise positions of the upper tensioning and fastening-inserting units in accordance with the length of the shoe in the jack are, except as hereinafter described, similar in construction to the corresponding mechanisms of the machine fully disclosed in the prior Letters Patent referred to above to which reference may be made for a complete disclosure of parts not fully illustrated and described in the present application.

The novel features of the shoe supporting jack, the means for supporting the jack, and the connections from the jack supporting means to the pattern cam mechanisms for imparting feeding movements to the jack and longitudinal tipping movements to the shoe to compensate for the longitudinal curvature of the shoe sole are not claimed herein since they form the subject-matter of United States Letters Patent No. 1,923,154, granted August 22, 1933, upon an application filed 70 in the name of Robert H. Lawson.

The upper tensioning and fastening-inserting units 54, 56 are each carried by a support having a cylindrical portion 110, Figs. 10 and 14, provided at its lower end with a flange 112 and at its upper end with a collar 114 clamped to the cylindrical portion 110. Each cylindrical portion 110 is positioned in a sleeve 116 of a bearing block 118 supported for forwardly and rearwardly swinging movement by a pair of trunnions 120, 122, carried by the head of the machine. The flange 112 and the collar 114 serve to prevent vertical movement of the upper tensioning and fastening-inserting units 54, 56, but permit the units to rotate about the approximately vertical axes of the cylindrical portion 110 and the sleeve 116.

In order that the units 54, 56 will have equal but opposite movements as they are swung toward and from each other, each block 18 has pivotally connected thereto a link 124, Fig. 7. The links 124 are of equal lengths and are pivotally connected to the blocks 18 for swinging movements about axes which are parallel to the axes of the trunnions 120, 122. The opposite ends of the links 124 are connected to the opposite ends of a lever 126 pivotally connected to the head 52 of the machine for swinging movement about a horizontal axis extending transversely of the head 52 intermediate between the trunnions 120, 122 of the bearing blocks 18.

Secured to the lower end of each cylindrical portion 110 are a pair of parallel plates 128, 130 for supporting the staple forming and inserting mechanism and the tack-driving mechanism and between which a pair of pincers or grippers 132 are carried.

Housed within each of the cylindrical portions 110 is a pair of slide members or cross heads 134, 136, Figs. 10 and 14, each having a semi-cylindrical outline. These slide members 134, 136 are moved lengthwise of the cylindrical portions 110 by mechanism hereinafter described and are effective to operate the staple forming and inserting mechanism, the tack-driving mechanism and the upper gripping pincers 132 respectively, regardless of, and without interference by swinging movement of the upper tensioning and fastening-inserting units 54, 56 about their trunnions 120, 122, or turning movement of the units about the axes of their cylindrical portions 110. To permit this turning movement each of the slide members 134, 136 is provided with a groove 138 parallel to the circumference of the slide member and receiving a block 140 having a cylindrical outer surface so as to permit rotation of the slides 134, 136 about their axes while the blocks 140 remain stationary. The blocks 140 are connected by links 142, 144 (Fig. 8) to the means for operating the staple forming and inserting mechanism, the tack-driving mechanism and the upper gripping pincers 132, respectively. The slide 134 is connected to the staple forming and inserting mechanism and the tack-driving mechanism by a link 146 and the slide 136 is connected to the gripping pincers 132 by a link 148, Fig. 10.

Staple forming and inserting means

The staple forming and inserting means of each unit 54, 56 is illustrated particularly in Figs. 14, 15, and 16. The side plates 128, 130 of each unit 54, 56 are provided with forwardly and downwardly inclined guideways for movable slides or

carriers 150 having mounted thereon the upper wiping means, the staple driving mechanism, and a portion of the staple forming mechanism. Pivoted at 152 to the side plates 128, 130, beneath 5 the carrier 150 is a lever 154 having an upwardly projecting portion 156 shaped and arranged to serve as an inside former for the staple. Each carrier or slide 150 is formed of two principal parts, an upper portion 158 and a cover plate 160, 10 the lower portion 162 of the forward end of which serves as a wiper to wipe the shoe upper 68 over the feather and into engagement with the rib of the insole 72. The upper portion 158 of the carrier 150 is shown in detail in Figs. 17, 18 and 19 and comprises a pair of parallel bars 164, 166 carrying at their forward ends a staple guiding nozzle or throat member 168 and between which are mounted for reciprocating movement an outside former slide 170, a driver slide 172, and an 15 operating slide 174. The driver slide 172 and the operating slide 174 have formed upon their opposite side portions tongues which extend into lengthwise grooves formed in the parallel bars 164, 166. The operating slide 174 is provided 20 with a rack 176 the teeth of which mesh with the teeth of a gear segment 178 formed upon the downwardly-extending arm 180 of a bell-crank lever 182 fulcrumed at 184 to the side plates 128, 130. The lever 182 is provided with a laterally-extending arm 186 to the outer end of which is 25 pivotally connected the lower end of the link 146. The driver slide 172 is provided with trunnions, one of which is shown at 188 (Figs. 15 and 16), to which are pivotally connected a pair of links 190, 30 the opposite ends of which are pivotally connected to the downwardly-extending arm 192 of a driver lever 194 fulcrumed at 196 to the side plates 128, 130 and having an upwardly-extending arm carrying a latch 198 arranged to engage 35 a latch 200 carried by a lever 202 fulcrumed at 204 to the side plates 128, 130 to hold the driver lever 194 in its rearmost position (Fig. 15). A driver 40 206 T-shaped in cross section is clamped at 208 (Fig. 15) to the driver slide 172 and passes through similarly shaped driver passages formed 45 in the outside former slide 170 and the nozzle or throat member 168.

The two wires 210 from which the staples are formed are fed to the units 54, 56 by mechanism 50 of the type disclosed in the prior Letters Patent No. 1,854,204 hereinbefore referred to through tubes 212 each having an adjustable end portion 214 threaded into the slide plate 128 (see particularly Fig. 10). Cooperating with the inside former 156 is an outside former comprising a pair of thin forwardly-extending plates 216, 218 which are spaced apart and which extend when the outside former slide 170 is in its rearmost position into the nozzle 168 to form with the inside former 156 a wire passage 220 in alignment with the outlet end 215 of the adjustable end portion 214 of the tubes 212 at the time the wire is fed. The plates 216, 218 are carried by the slide 170 and as the slide 170 is moved forward the wire is first severed by the plate 216 one edge of which 55 acts as a cutter and cooperates with the outlet end 215 of the adjustable end portion 214 to cut the wire before the forming of the staple begins. The feeding of the wires takes place soon after 60 the parts have been returned to their rearmost positions (Figs. 15 and 17). The cover plate 160 is provided with a slot 222 to permit entrance of the inside former 156 into the driver passage formed in the outside former slide 170. The lever 75 154 is provided with a cam surface 224 which,

when the parts are in their rearmost positions, lies in the path of movement of a cam surface 226 formed upon the wiper cover 160 and with a lug 228 at its rearmost end the upper surface 230 of which normally bears against a finished surface 232 formed upon the wiper cover 160. The lug 228 is provided with a lower inclined surface 234 which lies in the path of movement of a cam surface 236 formed upon the cover plate 160. Thus as the carrier 150 is moved toward and from the work, the lever 154 is swung positively first in a counterclockwise direction as viewed in Figs. 15 and 16 to move the inside former 156 out of the driver passage formed in the outside former slide 170 after a staple has been formed and then in a clockwise direction to move the inside former 156 into the driver passage of the slide 170 during the return movement of the carrier 150 and before the wire is fed into the wire passage 220. It will be understood that the slide 174 is operated in timed relation to the gripper mechanism to move the outside former slide 170 forwardly relatively to the carrier 150 to cause the plates 216, 218 to form a staple around the inside former 156 from a piece of wire presented thereto and then to impart forward and downward movement to the carrier 150 to cause the wiper 162 to wipe the tensioned upper 68 inwardly over the feather and into engagement with the rib of the insole 72 before a staple is inserted into the work and to return these devices to their rearmost positions after the driving of the staple. As illustrated, the operating slide 174 is provided at its forward end with a downwardly projecting portion 238 which extends between a pair of spaced upstanding lugs or projections 240, 242 formed on the outside former slide 170 and with a lug 244 depending from the median portion of the slide 174 and extending between the outside former slide 170 and the driver slide 172.

Referring more particularly to Figs. 14 and 15 which illustrate the various parts of the staple forming and inserting mechanism in a position of rest, it will be seen that each driver lever 194 is provided with a pair of adjustable blocks 246 mounted at opposite sides of the lever upon a rod 248 which extends through an arcuate slot 250 formed in the lever 194 concentric with the pivot 196. The rods 248 are held in adjusted position by nuts 252 threaded upon the opposite end portions of the rods and arranged to clamp the blocks 246 and the rods 248 in any position relatively to the levers 194 to which they may be adjusted. Each driver lever 194 is urged in a clockwise direction, Fig. 14, by a pair of coiled driving springs 254 mounted upon the hub portions of a pair of levers 256 pivoted at 196 to the side plates 128, 130 and having downwardly-extending arms 258 connected to the parallel bars 164, 166 of the carrier 150 by ball and socket connections. To limit the driving movements of the levers 194 under the influence of the springs 254 there are provided laterally-projecting stops or lugs 260 formed on the levers 256 and arranged to engage fiber disks 262 carried by the adjustable blocks 246. The levers 194 are provided with laterally-extending ears 264 carrying adjusting screws 266 the ends of which bear against the upper surfaces of the adjusting blocks 246. The blocks 246 may be adjusted relatively to the lever 194 to determine the position of the staple drivers 206 at the end of their driving strokes relatively to the nozzles 168 by movement of the screws 266. This adjustment is preferably made when the parts are in the positions shown in Fig. 16 and 150

since the extent of driving movement imparted to the lever 194 by the spring 254 is limited by the stop 260, the position of which is controlled by the position of the carrier 150 at the end of its 5 downward movement, it will be readily seen that the adjusted positions of the drivers 206 will remain fixed relatively to the nozzles 168 regardless of the thickness of the work or such small 10 variations as there may be in the extent of the movement of the carrier 150.

The presser feet 74, 76 are arranged to yield, during the inward movement of the carriers 150 to clamp the stock, to compensate for varying thicknesses of work and, accordingly, are pivoted 15 at 75 between the side plates 128, 130 and urged in a counterclockwise direction as viewed in Figs. 14, 15 and 16 by spring pressed plungers 77 bearing against the upper ends of a pair of upwardly-extending arms 79 with which each presser foot 20 74, 76 is provided. The presser feet 74, 76 are provided with stops 81 arranged to engage surfaces 83 formed on the side plates 128, 130 to limit counterclockwise movement of the presser 25 feet 74, 76 under the influence of the spring pressed plungers 77. In order that the legs of the staples will be guided properly relatively to clinching cavities 268 formed in a substantially vertical surface with which each presser foot 74, 76 is provided, each nozzle or throat member 168 30 is provided with a guide member 270 urged in a counterclockwise direction as viewed in Figs. 14, 15 and 16 by a spring pressed plunger 272 and having a downwardly projecting portion 274 corresponding in width to the distance between the 35 legs of the staple. The portion 274 of the guide members 270 lies in the driver passage of the throat member and after guiding the legs of the staple is lifted by engagement of the driver 206 therewith.

40 Rearward movement of the slides 174 is effective also to return the driver slides 172 to their rearmost positions the depending lugs 244 of the slides 174 engaging the slides 172 and the stops 260 on the levers 256 engaging the adjustable blocks 246 carried by the driver lever 194 so that as the levers 182 are swung in a counterclockwise direction, as viewed in Figs. 14, 15, and 16, the slides 172 and the levers 194 are moved into 45 latching position, the latch carrying lever 202 being operated at this time by means hereinafter described to hold the lever 194 in its rearmost position against the action of the spring 254.

By reference to Figs. 17, 18, and 19 it will be seen that the wiper covers 160 are provided with nose portions 276 arranged to bend the upper and the rib of the insole inwardly toward the body portion of the insole rearwardly of the presser feet 74, 76. The nose portions 276 are also provided with guideways or grooves 278 through 50 which the tacks are driven, the tacking mechanism being definitely located with respect to the wipers as will be hereinafter explained, to drive the tacks at these points. The portions 276 are provided with deflecting surfaces 280 arranged 55 to engage the tacks before they enter the work and to bend successive portions of them, as they are driven, in directions transversely of the rib of the insole inwardly toward the body portion of the last. It will be observed by reference to 60 Fig. 22 that the tacks are thus driven close to the base of the rib of the insole and serve to relieve the rib of the tension of the upper and to hold the overwiped margin of the upper flat upon the feather of the insole. It will also be evident 65 that the staples are driven in the same direction 70 75

as the overlaying movement of the wipers 162 and that they are thus inclined inwardly toward the base of the rib of the insole, the legs of the staples being clenched close to the base of the rib on the inner side thereof and the cross-bars of the staples being located on the outer side of the rib beneath the path of the inseam trimming knife and above the path of the welt attaching needle.

The formation of a staple

As shown in Fig. 17 the wire 210 from which the staples are formed is fed into the wire passage 220 between the inside former 156 and the outside formers 216, 218 when the parts are in their rearmost position. Upon forward movement of the slides 170 the members 216 sever the fed-in portions of wire and at the same time the outside formers 216, 218 engage the wire to press it against the face of the inside formers 156. By continued movement the outside formers form a substantially U-shaped staple as clearly shown in Fig. 19. During the formation of the staples the carriers 150 are held against movement by friction devices 221, Fig. 5, comprising flat springs 223 mounted on the side plates 130 and having their free ends bearing against brass plugs extending through apertures formed in the side plates 130 and bearing against the bars 166 of the wiper casings 150. The friction devices 221 perform a like function to restrain the carriers 150 from moving with the slides 170 at the start of the return movement of the operating slides 174, the slides 174 moving the slides 170 rearwardly relatively to the carriers 150 until the slides 170 engage pins 171 carried by the parallel bars 166 of the carriers 150 after which during continued movement of the slides 174 rearwardly the slides 170 move the carriers 150 away from the work. At the end of the forward movement 110 of the slides 170 relatively to the carriers 150 the staples are fully formed. At this time also the projections 240 formed on the slides 170 engage the rear faces 241 of the nozzles 168 and the outside former members 216, 218 are in engagement 115 with the surfaces 217, 219 formed on the staple guiding nozzles 168 thus forming continuous driver passages for the staples, Fig. 19. It will be understood that the driver passages in the slides 170 are in alignment with the driver 120 passages in the nozzles 168 from which the staples are driven into the work. By continued movement the slides 170 move the carriers 150 toward the work. As the carriers 150 are moved 125 toward the work the cam surfaces 226 engage the surfaces 224 formed on the levers 154 to swing the levers 154 in a counterclockwise direction as viewed in Figs. 14, 15 and 16 thereby moving the inside formers 156 out of the driver passages in 130 the outside former slides 170 and leaving complete staples in the driver passages ready to be 135 inserted into the work.

The tack inserting mechanism

The tack driving mechanism of each unit 54, 56, is illustrated particularly in Figs. 20 and 21 and comprises a driver bar slide 300 mounted for vertical sliding movement in a groove or way formed in the side plate 130. The slide 300 is bored longitudinally for the greater portion of its length for the reception of a cylindrical driver bar 302. At its lower end the slide 300 is provided with a reduced bore 316 into which extends a tack driver 304. The cylindrical driver 145 150

bar 302 surrounds the upper end of the driver 304 and is provided with a transverse slot to receive a block 306 the lower surface of which bears against the head of the driver 304 and the upper surface of which is concaved to fit the rounded end portion of a link 308 pivoted at its lower end to the driver bar 302 and at its upper end to the forward end of a lever 310 pivotally mounted upon a rod 312 supported by a pair of ears 315 extending upwardly from the side plate 128. At its lower portion the driver bar slide 300 is provided with a downwardly and inwardly inclined tack passage 314 converging toward and entering the bore 316 and into which tacks are delivered in successive charges through flexible tubes 318 from a distributor indicated generally by the reference numeral 320, Fig. 8, and mounted upon the head 52 of the machine. The distributor 320 may be of any suitable type such, for example, as that shown in United States Letters Patent No. 1,722,287, granted July 30, 1929, upon an application filed in the names of George Goddu and Fred L. MacKenzie. The distributor 320, Figs. 5, 6, and 8 comprises a tack pot 322 rotatably mounted upon a bracket 324 carried by the head 52 of the machine. The tack pot 322 is continuously driven by a belt 326 running from a pulley member 328 driven by suitable gearing from the head shaft of the machine. The distributor is provided with a raceway unit 330 having a pair of raceways and an oscillating separator blade 332. The separator blade is carried by a lever 334 mounted upon the bracket 324 and is provided with a laterally-extending arm 336 carrying a gear segment 338 the teeth of which mesh with a gear segment 340 loosely mounted upon a stud 342 carried by a bracket 324. The segment 340 has an operating arm 344 pivoted to a link rod 346 which is connected at its opposite end to the upwardly-extending arm of a lever 348 pivoted at 350 to the head of the machine and having a downwardly-projecting arm carrying a cam roll positioned in a cam track 352 formed in a cam member 354 mounted upon the head shaft of the machine. The configuration of the cam track 352 is such that the link rod 346 is operated once for each complete rotation of the head shaft of the machine to swing the separator blade 322 once across the ends of the raceways in the raceway unit 320 to separate a tack from each raceway and allow them to drop through passages 356, 358 into the tack tubes 318 which lead to the tack passages 314 formed in the tack carrying and driver bar slides 300. To retain the tacks to receive the action of the drivers 304 each driver bar slide 300 is provided at its delivery end below the junction of the passage 314 with the bore 316 with a nozzle 360 formed in halves divided vertically. The halves of the nozzle 360 are pivoted at 362 to the slide 300 and are held yieldingly together to form a contracted passage for the tacks, axially aligned with the bore 316, by a coiled spring 364 the arms of which bear against the outer surfaces of the halves of the nozzle.

In order to inspect the passage 314 and the lower end of the bore 316 the passage 314 is formed as a groove the open side of which is closed by a removable hook-shaped gate or clean-out piece 366, Figs. 20 and 21. The gate 366 is provided with a hook-shaped lower portion having a slot 392 formed therein and an upwardly-extending portion having a slot 398 formed in its upper end. The slot 392 is adapted to engage a pin 390 carried by the slide 300 and extending transversely of the passage 314 and about which the gate 366 may be swung into position to close the passage 314 and the lower end of the bore 316. The gate 366 is held in closed position by a bail 394 pivoted at 396 to the slide 300 and arranged to engage the slot 398 formed in the upper end of the gate 366. The slide 300 is provided with an arcuate surface 393 eccentric with respect to the pin 390 and arranged to engage a correspondingly shaped surface 395 formed upon the lower edge face of the gate 366 to limit swinging movement of the gate to close the passage 314. From the construction described it will be readily seen that the gate 366 may be removed by simply lifting the bail 394, swinging the gate 366 outwardly and removing it from the pin 390 to ascertain whether tacks are flowing properly to the nozzle 360.

The lever 310 is operated to impart tack driving movement to the driver 304 by a torsion spring 368 coiled about the hub of the lever 310 and having one end bearing against a pin 370 carried by the side plate 128 and the other end bearing against a laterally-extending arm 372 projecting from the median portion of the lever 310, Figs. 20, 21. Clockwise movement of the lever 310, as viewed in Figs. 20 and 21, is limited by a stop 382 carried by the side plate 130 and engaging a lateral projection 384 formed on the lever 310. The lever 310 is held in its uppermost position against the action of the spring 368 by a latch 374 formed upon the lever 202 which engages a latch 376 formed upon the arm 372 of the lever 310, Figs. 15 and 16. The lever 310 is unlatched to permit the driving of a tack substantially simultaneously with the release of the lever 192 my mechanism hereinafter described and is returned to its uppermost position substantially simultaneously with the return of the lever 192. As shown, the lever 182 is provided with a laterally-extending arm 378 to which is pivotally connected a rod 380 having a ball-shaped median portion 386 and a reduced end portion 388 extending through an aperture formed in the arm 372 of the lever 310. As the lever 180 is swung in a counterclockwise direction, Figs. 15 and 16, the ball-shaped median portion 386 of the rod 380 engages a spherical seat 385 formed upon the arm 372 of the lever 310 and as the lever 180 continues its counterclockwise movement the lever 310 is returned to its starting position after a tack has been driven into the work.

In order to facilitate presentation of the shoe upper to the grippers 132 the slides 300 are maintained in an out of the way position during the feeding movement of the work and are moved downwardly in response to inward movement of the carriers 150 into proper relation to the grooves 278 in the wiper covers 160 so that the tacks will be driven in the proper locations at the end of the overwiping operation. As shown in Figs. 15, 16 and 20 the carrier 150 carries a pin 282 extending through a slot 284 formed in the side plate 130 and into a slot 286 formed in the rearwardly-extending arm of a lever 288 fulcrumed at 290 to the side plate 130 and provided with a forwardly-extending arm 292 the front end of which is forked to engage a pin 292 carried by the slide 300. It will be evident that rearward movement of the carrier 150 and pin 282 will swing the lever 288 about its fulcrum to elevate the slide 300 and that as the

carrier 150 moves toward the work the slide 300 will be moved downwardly into proper relation to the grooves 278 before the driving of the tacks.

5 The driving mechanism

The power operated parts of the machine are driven from a motor 450 (Figs. 1 and 2) mounted on the top of the housing 452 of a controlling device or stop motion indicated generally by the reference character 454, the general organization of which is similar to that fully described in the prior Letters Patent No. 1,854,204 above mentioned. The controlling device or stop motion 454 is provided with a clutch member 456 mounted for movement into and out of driving contact with a clutch member 458 provided with an internal gear 459 connected to the motor 450 through a train of gears 460. The clutch member 456 is provided with a skew gear 462 the teeth of which mesh with the teeth of a skew gear 464 secured to one end of a shaft 466 extending through a bearing 468 formed upon the housing 452. Fast to the other end of the shaft 466 is a gear 470 the teeth of which mesh with the teeth of a gear 472 rotatably mounted upon the head 52, Figs. 6 and 9. The gear 472 meshes with a gear 474 formed upon the end of a shaft 476 which extends through the head 52 of a machine. It is this shaft 476 which operates the upper tensioning and fastening-inserting units 54, 56, as clearly shown in Figs. 8 and 9. The base 50 of the machine is provided with suitable bearings for supporting a transversely extending shaft 480 and a vertical shaft 482, Figs. 1 and 3, upon which is mounted for rotary and sliding movement relatively thereto a bank of pattern cams 484 supported upon a hollow shaft 492 surrounding the shaft 482 and to the upper end of which is secured a gear 488. Fast upon the right-hand end of the shaft 480 is a skew gear 486. The gear 486 meshes with a similar gear secured to the end of a vertical shaft 490 which is geared to the stop motion 454 in the same manner as in the machine of the prior Letters Patent No. 1,854,204 above mentioned, so that the shaft 480 is driven as long as the clutch member 456 is in power transmitting position. The gear 488 (Fig. 3) is arranged to mesh with any one of a group of gears 494 fast upon a vertical shaft 496 to the upper end of which is secured a gear 498 the teeth of which mesh with the teeth of a gear 500 carried by the controlling device 454.

The pattern cam shaft 482 is thus driven continuously so long as the clutch member 456 is in power transmitting position and the ratio of the gearing is such that nearly one complete revolution is imparted to the pattern cam shaft 482 while the shoe to be operated upon is lasted approximately from the heel breast line to the tip line at the toe of the shoe. The pattern cam shaft 482 is provided with a series of sets of cams as in the machine of the prior Letters Patent No. 1,854,204 referred to above, which when brought into operative position permit the machine to operate alternatively upon shoes which are rights and lefts and to operate alternatively upon shoes of several different styles. The different sets of cams are brought into operative position by a longitudinal adjustment of the cam shaft 482, the mechanism for producing this adjustment being the same as that disclosed in the prior Letters Patent No. 1,854,204 hereinbefore mentioned.

Connections from the driving mechanism to the stapling mechanism

Fast upon the shaft 476, as shown in Fig. 6, is a cam member 530 provided with a cam groove 532. A lever 534 is fulcrumed at 536 to the head 52 of the machine and provided at its rear end with a cam roll 538 positioned in the cam groove 532. The forward extremity of the lever 534 is pivoted at 540 to a cross-head 542 which is also pivoted at 544 to a lever 546 fulcrumed at 548 to the head 52 of the machine. The fulcrums 536, 548 are in vertical alinement as also are the pivots 540, 544 so that the crosshead 542 is maintained at all times horizontal as it is moved upwardly and downwardly by the rocking motion transmitted to the lever 534 by the cam member 530. The upper ends of the links 142 of the two fastening inserting units are pivoted, as shown at 550, to the cross-head 542 so that the mechanism just described is operative to swing the lever 182 about its fulcrum to operate the staple forming mechanism and to move the carrier 150 and the slide 300 toward and from the work and to return the staple inserting means and the tack driving means to their inoperative positions after the insertion of the staples and tacks.

The lasting pincers or grippers

Each of the upper-tensioning and fastening-inserting units 54, 56 is, as already stated, provided with a pair of pincers or grippers 132. These mechanisms each comprise a gripper jaw 400 (Figs. 15 and 16) having a long upwardly-extending shank 402 and a gripper jaw 404 fulcrumed at 406 to the jaw 400 and having a shorter upwardly-extending portion 408 provided with an inclined slot 410 through which passes a pin 412 carried by the lower end of the link 148 and also extending through an approximately vertical slot 414 formed near the bottom of the upwardly-extending shank 402 of the gripper jaw 400. The shank 402 of the gripper jaw 400 passes through a friction device 416, Fig. 10, carried by the cylindrical portion 110 of the unit and comprising a substantially T-shaped member the head of which consists of a tubular portion 418 in which the shank 402 has a sliding fit. The stem of the T is mounted in a hole bored in the unit 110 for rocking movement about a substantially horizontal axis and houses a spring-pressed plunger 420 bearing upon the shank 402 and providing sufficient friction so that when the link 148 is moved upwardly the shank 402 and the gripper jaws will be held against upward movement until after the gripper jaws 400, 404 have closed upon the shoe upper. When, however, the gripper jaws can move toward each other no further, continued upward movement of the link 148 moves the gripper jaws bodily upwardly, notwithstanding the friction applied to the shank 402 of the gripper jaw 400, and the shoe upper 68 is pulled upwardly relatively to the last 70. This takes place immediately before the cover plate 160 of the carrier 150 wipes the shoe upper inwardly over the feather and into engagement with the rib of the insole 72, after which a staple is driven as indicated at 422 in Fig. 22 and the hold of the gripper jaws 400, 404 upon the shoe upper is released.

Transverse movement of the gripper jaws relatively to the upper-tensioning and fastening inserting units is at all times limited to swinging movement about the substantially horizontal axis of the friction device 416 and the angular

extent of this swinging movement is limited by a surface 424 formed upon a cam piece 426 secured to the side plate 130, as best shown in Fig. 15.

5 *The pincer or gripper operating mechanism*

The mechanism for operating the grippers 132 of the lasting mechanism comprises a lever 560 also fulcrumed at 536 to the head 52 of the machine and rocked by a cam roll 562 positioned in a cam track 564 formed in a cam member 566 fast upon the shaft 476 (Fig. 7). The forward extremity of the lever 560 carries the fulcrum 568 of a crooked lever 570, the rear extremity of which is pivoted at 571 to a downwardly-extending rod 572 (Figs. 1, 7 and 8), which passes through a block 602 pivotally connected to the forward end of a lever 604 pivoted to the head 52 at 606 and then through a plate 601 secured 20 to the head 52. The lower end of the rod 572 passes through an opening in the end of a substantially horizontal lever 574 fulcrumed at 576 to the frame 50 and formed of two parts 578, 580 pivotally connected at 582 and supported from the frame 50 of the machine by a spring 584. The part 578 of the lever 574 is yieldingly held in alinement with the part 580 by a spring 586 surrounding a rod 588 secured to the left-hand portion 580 of the lever 574. The 30 spring 586 bears at one end upon the portion 578 of the lever 574 and at the other end upon a wing nut 590 threaded on the rod 588. The right-hand end of the portion 580 of the lever 574 is connected by a link 592 with a lever 594 fulcrumed at its rear end to the frame 50 and having a cam roll 596 engaging the surface of a cam 598 (Figs. 1 and 7) mounted upon the shaft 480. The cam 598 is arranged to pull the portion 580 of the lever 574 downwardly against the action of the spring 584 and to hold it down during a portion of each revolution of the shaft 480. This downward movement takes place when the upper-tensioning and fastening-inserting units pass the forward end of the shank 45 portion of the shoe and is operative, as herein-after explained, to apply a greater tension to the shoe upper when operating along the ball and forepart of the shoe than while operating upon the shank.

50 A portion of the rod 572 is surrounded by a spring 600 bearing at its upper end against the plate 601 and at its lower end against a washer 608 surrounding the rod 572 and supported against downward movement relatively to the rod 572 by a nut and lock nut 610. A similar washer 612 and nut and lock nut 614 are located at the lower extremity of the rod 572, the portion of the rod 572 between the nuts 610 and the washer 612 passing through a hole in the outer extremity of the part 578 of the lever 574. Thus, when the lever 574 is rocked downwardly by the cam 598, its extremity engages the washer 612 and pulls the rod 572 and the rear end of the lever 570 downwardly with a force transmitted through the spring 586. The spring 586 is much stiffer than the spring 600. As it is the spring 600 which limits the tension which can be applied to the shoe upper while operating along the shank and the spring 586 which limits 65 the tension applied to the shoe upper while operating about the ball and forepart, the desired relatively light tension while operating along the shank and the heavy tension while operating along the ball and forepart are attained.

70 At its forward extremity the lever 570 is piv-

oted at 616 to a cross-head 618 (Fig. 7). The cross-head 618 is pivoted vertically above the pivot 616 to a link 620 which link, vertically above fulcrum 568, is pivoted to a lever 622 fulcrumed at 624 to the head 52, and to a link 626 pivoted also to levers 560 and 570 at 568. Thus, the cross-head 618 is maintained horizontal as it is moved up and down by the rocking of the levers 560 and 570. The cross-head 618 is connected at its extremities by the links 144 to the grippers 132 of the two upper-tensioning and fastening-inserting units.

As clearly shown in Fig. 8 the lever 604 is maintained in a horizontal position by a pair of toggles 628, 630. The toggle 628 is pivoted to the forward end of the lever 604 at 629. The toggle member 630 is pivoted to the base 52 at 632. The toggles 628, 630 are pivotally connected at 634 to the head 636 of a rod 638 which extends through an opening in the head 52 of the machine and is pivotally connected at its opposite end to a lever 640 pivotally connected at 642 to the head 52. The toggles 628, 630 are held in straightened position by a spring 644 which surrounds the rod 638 and bears at one end 100 against the head 52 of the machine and at the other end against the head 638 of the rod 638. As the lever 560 is rocked in a clockwise direction (Fig. 7) the rod 572 is held against heightwise movement by the spring 600 so that the 105 tension which is applied to the shoe upper while operating along the shank portion is comparatively light. When, however, the lasting units approach the ball and forepart of the shoe the lever 574 is moved downwardly by the cam 598 110 until its forward end comes into engagement with the washer 612 at which time the rod 572 is held against heightwise movement by the spring 586 so that a heavy tension is applied to the shoe upper along the ball and forepart. 115 The rod 572 is formed in two parts connected by a turnbuckle 646 and lock nuts 648. As the lever 560 is rocked in a counterclockwise direction (Fig. 7) the rod 572 is moved downwardly under the influence of the springs 600, 586 until 120 the nut 648 comes into engagement with the upper surface of the block 602 after which during continued counterclockwise movement of the lever 560 the pincers 132 are returned to their lowermost positions.

125 It will be evident that by adjusting the turnbuckle 646 and lock nuts 648 the lowermost positions of the pincers 132 may be varied to determine the point relatively to the insole at which the pincers grip the shoe upper. In operating on 130 shoes having scant uppers, that is shoes the uppers of which do not extend above the feather of the insole, it will be evident that the pincers 132 must be adjusted low enough so that they can grip the opposite edges of the shoe upper firmly 135 even though the upper is below the feather of the insole. In order to insure that sufficient up-draw movement will be imparted to the pincers when operating particularly on scant uppers so that they may swing in their appointed paths 140 without damaging the rib of the insole or interfering with the inward movement of the wipers, means is provided for imparting a positive heightwise movement to the grippers 132 if the extent of their impositive movement is insufficient to 145 carry them above the top of the rib of the insole. As clearly shown in Fig. 8, the rod 572 is provided, between the block 602 and the plate 601, with a washer 621 and a nut and lock nut 623. As the lever 560 is swung in a clockwise direction the 150

rod 572 is permitted to move upwardly against the action of either the spring 586 or the spring 600 until the washer 621 strikes the block 602 after which, during continued clockwise movement of the lever 560, a positive heightwise movement is imparted to the pincers 132. By adjusting the position of the washer 621 relatively to the block 602 the extent of heightwise movement imparted to the pincers 132 may be varied. Thus the limit of movement of the pincers 132 away from the body of the insole may be maintained at a greater height than that of the top of the rib of the insole regardless of the point relatively to the feather of the insole at which the pincers grip the shoe upper.

Means will now be described for rendering the grippers 132 inoperative as different portions of the shoe upper are presented to the fastening-inserting instrumentalities of the units 54, 56. This is a relatively important feature of the invention since it facilitates feeding of the work through portions of the upper which have previously been tensioned and secured in lasted relation by temporary lasting tacks. Referring now particularly to Figs. 5 and 8, it will be seen that the lever 640 is provided with a cam roll 650 yieldingly held in engagement by the spring 644 with a cam member 652 mounted for free rotary movement upon a stud 654 carried by the head 52. Also mounted upon the stud 654 is a ratchet plate 656 adjustably connected to the cam member 652 by slot and screw connections 658 and a lever 660 carrying a pawl 662 spring pressed downwardly into engagement with the periphery of the ratchet plate 656. The lever 660 is connected by a link 664 to the downwardly-extending arm 666 of a lever 668 pivoted at 670 to the head 52 and having an upwardly-extending arm pivotally connected at 672 to the laterally-extending arm 674 of the lever 348. Thus it will be seen that rotation of the cam 352 is effective to reciprocate the rod 664 and to oscillate the pawl 662 once during each complete rotation of the head shaft thereby rotating the plate 656 and the cam 652 step by step in a clockwise direction (Fig. 5). The plate 656 is provided with ratchet teeth corresponding in number to the cycles of operation of the upper-tensioning and fastening-inserting units 54, 56 in lasting a shoe from the heel breast line to the tip line. The configuration of the cam 652 is such that the lever 640 is swung in a counterclockwise direction (Fig. 8) to break the toggle 628, 630 when it is desired to prevent downward movement of the pincers 132 into operative position. As previously stated counterclockwise movement of the lever 560 (Fig. 9) is effective to move the rod 572 downwardly until the nut 648 contacts with the block 602 after which the pincers 132 are returned to their lowermost positions. After the breaking of the toggles 628, 630 however the block 602 is free to move downwardly with the rod 572 so that the lever 570 is swung in a clockwise direction about its fulcrum 616 during counterclockwise movement of the lever 560, the friction devices 416 (Fig. 10) holding the pincers 132 against downward movement after the link 148 has been lowered sufficiently to close the jaws 400, 404.

70 The wire-feeding means

The two wires 210 from which the staples are formed are supplied from a pair of reels 1512, 1514 (Figs. 2, 5 and 6) carried by a bracket 1516 mounted upon the head 52 of the machine. From the reels 1512, 1514 the wires 210 pass through

80 a pair of guides 1518, 1520 carried by the bracket 1516 and then downwardly to and through tubes 1524 (Figs. 11, 12 and 13) to feed rolls 1526, 1528 (Fig. 12), a pair of which are carried by each of the upper-tensioning and fastening-inserting units 54, 56. From the feed roll 1526, 1528 each wire passes through the corresponding tube 212 to its outlet 215 as already described. The means for operating the two pairs of feed rolls 1526, 1528 of the staple forming and inserting units 54, 56 85 need not be described herein in detail, since it is substantially the same as the means fully described in the prior Letters Patent No. 1,854,204 hereinbefore mentioned. As more fully disclosed in said prior Letters Patent No. 1,854,204, the feed rolls 1526, 1528, are rotated by a pawl and ratchet arrangement 1530 (Fig. 14) clamped to the outer end of a shaft 1532 geared to a rod 1534 connected to a cam 1536 mounted at the right-hand side of the head 52 instead of at the left-hand side as in the machine of the prior Letters Patent No. 1,854,204 hereinbefore mentioned. Rotation of the cam 1536 is effective to reciprocate the rod 1534 and thus to drive the feed rolls 1526, 1528, through the pawl and ratchet 1530 in 90 a step-by-step manner to feed appropriate lengths of wire to the units 54, 56.

The driving of the staples and tacks

95 For operating the latches 200, 374 to release the levers 194, 310 for the staple-inserting and tack-driving operations each unit 54, 56 is provided with a lever 680 fulcrumed at 682 to the side plates 128 and having a forwardly-extending arm 684 provided with a gear segment 686 the teeth of which mesh with teeth formed upon the rod 1534 (Fig. 14). The lever 680 has a rearwardly-extending arm to which is pivotally connected a link 688 the upper end of which is pivotally connected to the laterally-extending arm 690 of the 100 latch carrying lever 202. The configuration of the cam 1536 is such that after the parts have been returned to their rearmost positions, (Figs. 14 and 15), the rod 1534 is moved downwardly to rotate the feed wheels 1526, 2528, to feed predetermined lengths of wire to the units 54, 56. Downward movement of the rod 1534 causes the lever 680 to swing in a counterclockwise direction as viewed in Fig. 17 and through link 688 to cause clockwise movement to be imparted to the 105 latch carrying lever 202 to swing the latches 200, 374 inwardly into engagement with the latches 198, 376 carried by the levers 194, 310, respectively. Release of the levers 194, 310, for the staple-inserting, and tack-driving operations is 110 effected substantially simultaneously in response to a counterclockwise movement imparted to the latch carrying lever 202 by upward movement of the rod 1534. Upward movement of the rod 1534 does not take place, however, until after the carrier 150 has been moved toward the work to cause the wiper 160 to wipe the tensioned upper 68 over the feather and into engagement with the rib of the insole 72.

115 The transverse positioning of the shoe

120 The presser feet 74, 76 serve not only to limit upward movement of the shoe and as anvils against which the staples are clenched, but also are utilized to position the shoe transversely, at 125 all times after the jacking of the shoe is completed, being spring-held in engagement with the rib at opposite sides of the insole. For this purpose the bearing block 118 of the sleeve 116 of the rear upper-tensioning and fastening-inserting 130

unit 56 is secured to the shaft 120 by a taper-pin 1462 (Fig. 10) and a downwardly-extending lever or rock arm 1464 (Figs. 5 and 10) is secured to the outer end of the shaft 120. A tension spring 1466 is anchored at one end to the lower portion of the lever 1464 and at the other end to a lever 1468 secured to a shaft 1470 extending transversely of the head 52. Secured to the opposite end of the shaft 1470 is a lever 1472 (Fig. 6) connected by a link or rod 1473 to a lever 1474 fulcrumed at the rear to a stationary part of the machine and carrying a cam roll 1476 engaging with a cam 1478 fast upon the shaft 480 (Figs. 1 and 2). The cam 1478 is formed to permit upward movement of the rod 1473 under the influence of the spring 1466 while operating along the shank portion of a shoe so that the presser feet 74, 76 will be pressed lightly against the rib of the insole while operating along the shank. As the operation passes from the shank portion to the ball portion of the shoe, however, the rod 1473 will be pulled downwardly by the cam 1478 so that the spring 1466 will move rearwardly, separating the presser feet 74, 76 and still holding them with a suitable pressure against the rib of the insole while operating upon the wider portions of the shoe. 80

The upper-tensioning and fastening-inserting units 54, 56 are held solidly in position with the anvil surfaces of the presser feet 74, 76 against the rib of the insole at the time that fastenings are inserted by locking mechanism indicated generally at 1480 (Fig. 7) the construction of which and likewise that of its operating mechanism are substantially like what is disclosed in the prior Letters Patent No. 1,854,204 above mentioned. 85

Automatic means is provided operating in timed relation to the longitudinal movements of the shoe for turning the units 54, 56 about axes extending approximately at right angles to the surface of the insole of the shoe operated upon to maintain the shoe upper engaging surfaces of the gripper jaws 132 substantially parallel to the portion of the shoe upper being operated upon and to cause the staple-inserting means to operate in paths substantially normal to the rib of the insole and the tacks to be inserted close to the base of the rib of the insole regardless of the edge curvature of the sole of the shoe. As has already been pointed out the upper-tensioning and fastening-inserting units 54, 56 are provided with approximately vertical cylindrical portions 110 mounted in correspondingly shaped and positioned sleeves 116 each of the cylindrical portions 110 having clamped to its upper end a collar 114. The collars 114 are provided with balls 1600 to which are connected links 1602, 1604 (Figs. 4, 9 and 14) extending transversely of the machine. The link 1602 which controls the turning movement of the forward unit 54 is connected at its left-hand end to the forwardly-extending arm of a bell-crank lever 1606 which lever is also provided with a transversely-extending arm pivoted to a rearwardly-extending link 1608. At its rearward end the link 1608 is connected to an arm 1610 of a bell-crank lever 1612 fast upon the upper end of a vertical rock shaft 1614 mounted in bearings carried by the head 52 of the machine and having secured to its lower end a lever 1616 connected by a link 1618 to a lever 1620 fast upon the upper end of a rock shaft 1622. A spring 1624 tends to move the link 1608 rearwardly thereby tending to rock the upper-tensioning and fastening-inserting unit 54 in a counterclockwise direction as viewed from 90

above (Fig. 9). A similar train of connections from the link 1604 to a shaft 1626 parallel and adjacent to the shaft 1622 tends to move the upper-tensioning and fastening-inserting unit 56 in a clockwise direction as viewed from above. Turning now to Fig. 3, it is observed that the shafts 1622, 1626, are provided near their lower ends with a pair of rock arms 1628, 1630 connected, respectively, by links 1632, 1634 to a pair of levers 1636, 1638. The levers 1636, 1638 are fulcrumed for turning movement upon the shaft 496 and are provided with inwardly and rearwardly-extending arms carrying at their extremities rolls engaging appropriately formed cam members of a bank of pattern cams 484 fast upon the hollow shaft 492 surrounding the shaft 482. The cams which engage the rolls of the levers 1636, 1638 are of such configuration as to turn the upper-tensioning and fastening-inserting units 54, 56 about their approximately vertical axes in such a way as to maintain the line of drive of the staples at all times in planes substantially normal to the rib of the insole, the tacks being inserted in the angle between the rib and the feather of the insole. 95

The jack

The jack 58 of the illustrated machine is provided with heel and toe rests pivotally mounted so as to permit a tipping movement of the shoe about an axis extending longitudinally of the shoe in substantially the plane of the sole. Except for the construction which provide for a lateral adjustment of one or both of these rests, the jack 58 is the same in the construction and arrangement of its parts as the jack disclosed in applicant's pending Letters Patent of the United States No. 1,923,154, granted August 22, 1933, on an application filed in my name. As clearly shown in Fig. 1 the jack 58 comprises a substantially U-shaped upper portion having a pair of upwardly-extending arms 850, 852 and a downwardly-extending spindle 854 connected to the support 800 by a gimbal or universal joint. The toe rest for the shoe comprises a suitably shaped block 856 mounted upon a bracket 858 which is pivotally supported in the arm 850 of the jack. The pivotal axis of the bracket 858 is arranged so that it is in line substantially with the longitudinal center line of the bottom of a shoe supported on the jack. In order to permit a lateral adjustment of the block 856 so as to produce a corresponding lateral shift on the bottom of the shoe with relation to the pivotal axis about which the bracket 858 swings, the block 856 is mounted in a laterally-extending guideway formed in the bracket 858 and is held in the desired lateral position in the guideway by means of a clamping screw 860 extending through a slot formed in the bracket 858 and threaded into the block 856. The heel rest comprises a last pin 862 which extends upwardly from a bracket pivotally supported in line with the pivot of the bracket 858 upon a longitudinally adjustable bar 864 mounted to slide in the upper end of the arm 852 of the jack 58. In order to permit a lateral adjustment of the last pin 862 with a corresponding shift of the heel portion of the shoe with relation to the axis about which the heel and toe rests swing, the supporting bracket for the heel pin 862 is made in two parts 866 and 868. The part 866 from which the heel pin projects being pivotally mounted at the lower end of the part 868 on a vertical pivot bolt 870 thus permitting the part 866 to be swung laterally with relation to the part 868. In order 100

to hold the part 866 in any position to which it may be adjusted, a spring pressed locking pin 872 is mounted in the part 866 and arranged to engage any one of a series of holes formed in the 5 lower end of the part 868. The lateral adjustment of the toe and heel rests permits the bottom of the shoe to be brought into a position in which the longitudinal center line of the sole corresponds substantially with the longitudinal axis 10 about which the shoe is tipped by the pressure of the sole against the abutments 74, 76 of the upper-tensioning and fastening-inserting units 54, 56. Thus the shoe sole can be forced with equal pressure against the abutments 74, 76 and the shoe 15 can be securely held at both sides whether it is a right or a left shoe or a shoe having an excessive swing. The lateral adjustment of the heel rest is of special value when shoes provided with narrow shanks are to be operated upon. The jack 20 58 of the illustrated machine is provided with shoe jacking and unjacking mechanism automatically actuated from a pulley 896, mounted at the upper end of the jack support 800, through a gimbal joint and a shaft 898 extending upwardly through 25 the jack spindle the construction and operation of the jacking and unjacking mechanism being the same as that disclosed in Letters Patent No. 1,923,154 hereinbefore mentioned. The pulley 896 is rotated by a cable 900 which passes about 30 the pulley 896 and passes rearwardly and to the left and then downwardly about a pulley 902 and beneath a pulley 904 secured to a weight 906. The other end of the pulley extends rearwardly and passes about a guide roll 908 mounted upon the 35 end of a freely swinging arm 910 pivoted to the base 50 of the machine and then to the right about a large pulley 912 to which the end of the cable is secured. The pulley 912 is rigidly secured to a spur gear 914 the two being mounted 40 upon a short shaft 916 (Fig. 3) carried by the base 50 of the machine near the front right end corner of the machine as clearly shown in Figs. 1 and 3. The gear 914 meshes with a pinion 918 fast upon the lower end of the shaft 490. From 45 the pulley 904 the cable 900 passes upwardly and is connected to the end of a chain 920 which continues upwardly and about a pulley 922 carried by the frame 50 then horizontally forward about a pulley 924 carried by a bracket 926 secured to 50 the base 50 then laterally about a pair of pulleys 928, 930 carried by a lever 932 known as the fulcrum lever and then to the left to an anchorage 934 on a horizontal lever 936 known as the feed lever the rear end of which is fulcrumed at 938 55 at the rear left-hand side of the machine for horizontal swinging movement.

Jack supporting structure

As previously stated the illustrated machine is 60 provided with a jack 58 arranged to support a last 70 upon which are assembled a shoe upper 68 and an insole 72 as best shown in Fig. 6. The jack 58 is connected by means of a universal or gimbal joint to the upper end of a vertically movable slide 800 rectangular in cross section and mounted in a guideway formed in a carrier 802, Figs. 1 and 2. The carrier is provided with a series of rolls 804 which bear against the four sides of the slide at its upper and lower ends and 65 thus hold the slide firmly against displacement laterally in any direction while permitting it to slide freely in a vertical direction. The jack support or slide 800 is yieldingly urged upwardly to press the insole 72, carried by the last 70, 75 against the abutments 74, 76 of the upper-ten-

sioning and fastening-inserting units 54, 56 by a comparatively long spring 806 located within the support 800 which is made hollow to receive it. The spring 806 bears at its upper end against a shoulder, formed in the support 800 and at its lower end against a disk 808 supported upon a screw 810 adjustably mounted in the carrier 802. To permit a comparatively wide range in the up and down movement of the support 800 without materially affecting the force with which the shoe is pressed against the abutment 74, 76, the spring 806 may consist of a number of nested spirals each formed of comparatively light wire but by their united action exerting the required upward force on the support. The carrier 802, in which the jack support 800 is mounted for vertical sliding movement, is mounted for horizontal sliding movement on the frame 50 of the machine. As illustrated the carrier 802 is provided with a pair of rearwardly-extending arms 812, 814 each carrying a pair of widely separated grooved pulleys 816 arranged to engage the upper end lower V-shaped edges of a pair of rails 818, 820 secured to the front of the base 50 of the machine. Thus, the carrier 802 is securely held 100 against displacement and is permitted to slide freely in a direction extending longitudinally of the shoe in the jack. In the illustrated machine sliding movements of the carrier 802, to tip the shoe about the point of operation so as to maintain the bottom of a shoe in the proper plane longitudinally of the shoe, are produced through connections operating from the pattern cam shaft 482 comprising a chain 822 extending across the front of the machine (Figs. 1 and 3) 110 and adjustably connected to the carrier 802 by an eccentric bolt 824 mounted in a rearwardly-extending arm 826 of the carrier 802. The chain 822 passes about a pulley 828 pivoted to the forward end of one arm of a bell crank lever 830 mounted 115 on the shaft 496. The bell crank lever 830 is provided with a rearwardly-extending arm carrying a cam roll arranged to engage one of a series of cams on the pattern cam shaft 482. From the pulley 828 the chain 822 extends across the front 120 of the machine and is secured to the base 50 at 832. It will be readily seen that movement of the pulley 828, in a counterclockwise direction, as viewed in Fig. 3, will move the carrier 802 through the chain 822 a distance equal to twice 125 the distance moved by the pulley 828. The carrier 802 is moved in the opposite direction by connections comprising a chain 834 also secured to the arm 826 of the carrier 802 and which passes about a pulley 838 secured to the base 50 of the 130 machine and then to one end of a long horizontal spring 840 to the other end of which is connected one end of a chain 842 which passes about a pulley 844 and is connected at its other end to one end of a spring 846 the other end of which is 135 connected to the base 50 of the machine by a short chain 848.

Means for locking the jack support against downward movement

The illustrated machine is provided with means for locking the jack support against downward movement during each operation of the upper-tensioning and fastening-inserting units 54, 56. As illustrated in Fig. 2 this locking means comprises a pinch dog 874 fulcrumed on a shaft 876 mounted in the carrier 802 and extending laterally of the carrier parallel to one side of the support 800. The pinch dog 874 is arranged to engage one side of the support 800 to prevent down- 150

ward movement of the support and in order to receive the thrust exerted by the pinch dog on the support 800 abutments 878 are provided which are adjustably mounted in the carrier 802 at the opposite side of the support from the pinch dog. The pinch dog 874 is operated to lock and release the jack support 800 in timed relation to the operation of the upper-tensioning and fastening-inserting units 54, 56, by a cam 880 mounted on the head shaft 476 (Fig. 6) through connections comprising a lever 882 fulcrumed on the shaft 1470 and having a rearwardly-extending arm connected by a rod 884 to the rearwardly-extending arm of a lever 886 fulcrumed to the base 50 of the machine and having a forwardly-extending arm 888 engaging the end of a rearwardly-projecting arm 890 with which the pinch dog 874 is provided. The lever 882 is provided with an upwardly-extending arm carrying a cam roll 892 engaging the cam 880. A spring 894 connected at one end of the rearwardly-extending arm of the lever 886 and at the other end to the frame 50 of the machine acts to hold the pinch dog 874 in a locking position while movement of the locking dog in a direction to release the jack support is produced positively through the cam 880 and connections therefrom to the arm 890 of the pinch dog 874. Since the carrier 802 is mounted for movement on the frame of the machine in a direction extending longitudinally of the shoe, the arm 888 of the lever 886 is extended in the direction of movement of the carrier and is provided with a slot to receive the end of the arm 890.

The work-feeding means

Means, which will now be described, is provided for moving the jack 58 to the left, transversely of the machine, to present a shoe upon a last carried by the jack to the upper-tensioning and fastening-inserting instrumentalities of the units 54, 56. For this purpose the upper end of the arm 850 of the jack 58 is connected by a link 940 to the forward end of the feed lever 936. (See particularly Figs. 3 and 7). The median portion of the lever 936 is connected by links 944 and 946 to the rearwardly-extending end of a large horizontal bell crank lever 942 fulcrumed at 947 near the top of the base 50 of the machine. The forward arm of the bell crank lever 942 carries a cam roll 949 bearing against a cam 950 at the upper end of the bank of pattern cams mounted on the shaft 482 and held in engagement with the cam 950 by the weight 906. The cam 950 is of such a configuration that as it rotates the lever 936 moves step by step from right to left, in a clockwise direction as viewed in Fig. 3, thereby feeding the jack step by step to the left, the upper-tensioning and fastening-inserting mechanisms of the units 54, 56 operating upon the shoe during the pauses between the successive steps of feeding movement. It should be noted, however, that in order to insure the absence of wrinkles in the shoe upper in the neighborhood of the heel breast line where the lasting operation is started, the cam 950 may be made of such a configuration as to cause a short feeding step after the grippers 132 have seized and tensioned the upper but before the first fastenings are inserted. Except for this first cycle of operation of the upper-tensioning and fastening-inserting mechanisms the machine operates to cause the grippers 132 to grip and tension the shoe upper and then to insert a staple through the shoe upper and into the rib of the insole without intervening feeding movement.

In order to control the feeding movement of the jack 58 in accordance with the size of the shoe operated upon so that the lasting operation may be performed in an unvarying number of cycles irrespective of the size of the particular shoe operated upon, pantograph mechanism is provided, controlled by the size of the shoe placed in the jack 58. In order to set the pantograph mechanism, which is of the same type as that disclosed in the prior Letters Patent No. 1,854,204 referred to above, the shoe jacking and unjacking mechanism of the jack 58 is provided with a gage 962 in the form of a ball movable toward the toe block 856 an amount determined by the size of the shoe in the jack 58 (Fig. 4). The ball 962 is arranged to engage against a surface 964 to which it is led by a pair of converging ribs 966 formed on a plate 968 at the end of a rod 970 mounted for forward and rearward sliding movement in guides carried by or formed in the top of the base 50 of the machine. The lengthwise movement of the rod 970 is controlled by mechanism which may be and preferably is of the type disclosed in the prior Letters Patent No. 1,854,204 hereinbefore mentioned. For present purposes, it is sufficient to note that after the shoe has been placed in the jack, the operator takes hold of the jack and swings it rearwardly, bringing the ball 962 into position between the ribs 966 and then permitting it to rise under the influence of the spring 806 into engagement with the surface 964. As the position of the ball 962 varies according to the length of the shoe in the jack, the position of the jack transversely of the machine is controlled in accordance with the size of the shoe. The larger the shoe the further the arm 850 of the jack 58 will be moved to the right and the shorter the shoe the further to the left. Thus, on account of the connection between the jack 58 and the feed lever 936, the position of the feed lever 936 at the time the machine is started will depend upon the size of the shoe in the jack and the larger the shoe the further the forward end of the lever 936 will be swung to the right.

The pantograph mechanism

The pivotal connection between links 944 and 946 (Fig. 3) is connected by a link 948 to a point near the rearward end of the fulcrum lever 932 which is pivoted at its forward end for horizontal swinging movement to the underside of the top of the base 50. The extreme rearward end of the fulcrum lever 932 is pivoted to a rod 954 mounted for sliding movement in a sleeve 956 fulcrumed at 958 to the rear of the base 50 and carrying a pair of pivoted dogs 960 arranged, when swung in one direction, to clamp the rod 954 in the sleeve 956 and, when swung in the other direction, to release the rod 954 for sliding movement in the sleeve 956. The dogs 960 are normally held in position to clamp the rod 954 to the sleeve 956 but are moved to releasing position for an instant as the machine is started so as to permit the relation of the rod 954 to the sleeve 956 and consequently the position of the fulcrum lever 932 and the position of the link 948 to be varied according to the length of the shoe in the jack. For this purpose the forward ends of the dogs 960 are provided with pins 972 engaged in slots formed in the ends of a bar 974 pivoted to a forwardly-extending sleeve 976 (Fig. 3) in which is housed

a spring 978 bearing at its forward end against an internal shoulder formed at the end of the sleeve 976 and at its rearward end against a shoulder formed on a rod 980 which passes through the spring 978 and the sleeve 976 and is pivoted at its forward end to the right-hand end of a horizontal swinging lever 982 fulcrumed beneath the top of the base 50 and connected intermediate its ends by a link 984 with the left-hand end of a lever 986 also fulcrumed beneath the top of the base 50. While the machine is in operation the lever 986 is held latched in the position shown in Fig. 3 by a spring-held latch 988 which engages a lug 990 formed on the lever 986. When, however, the jack 58 is moved into operative position preparatory to the starting of the machine, the latch 988 is swung in a counterclockwise direction, as viewed in Fig. 3, by mechanism of the type disclosed in the prior Letters Patent No. 1,854,204 above mentioned, thus releasing the lever 986 and permitting the rod 980 to move rearwardly thereby releasing the tension of the spring 978. This permits rearward movement of the bar 974, a light tension spring 992 being connected at one end to the middle of the bar 974 and at the other end to the base 50 of the machine back of the bar 974 in order to insure sufficient rearward movement of the bar 974 to release the dogs 960. This releases the rod 954 from the sleeve 956 and permits the fulcrum lever 932 and consequently the link 948 and the connection between the links 944 and 946 to move to the positions necessary for the operation upon the particular shoe in the jack 58. Mechanism for then operating the dogs 960 to latch the rod 954 to the sleeve 956 is operated by the subsequent depression of a treadle 994 with which the machine is provided the depression of which also starts the operation of the upper-tensioning and fastening-inserting mechanisms and the jack feeding mechanisms in the same manner as in the machine of the prior Letters Patent No. 1,854,204 referred to above.

45 The treadle connections

The treadle 994 of the machine is shown in Figs. 1 and 2. It is fulcrumed at 996 and is normally urged in an upward direction by a spring 998 anchored at one end to the treadle and at the other end to the base 50. The treadle 994 is connected through a vertical rod 1000 with a bell crank lever 1002 at the upper left-hand front corner of the base 50. The bell crank lever 1002 is connected by a link 1004 with the left-hand end of a slidably mounted rod 1006 (Figs. 1 and 3) extending transversely of the machine and provided with an upstanding pin 1008 (Fig. 3) which serves, when the treadle is not depressed, to limit upward movement of the treadle under the action of the spring 998 by engagement with a lug 1010 formed on the under side of the top of the base 50. When the treadle is depressed, however the pin 1008 moves to the right and engages the lever 986, which at that time extends forwardly across the rod 1006 by reason of the previous release of the latch 988. The movement of the pin 1008 to the right returns the lever 986 to the position in which it is shown in Fig. 3, thus swinging the right-hand end of the lever 982 forwardly and causing the dogs 960 to clamp the rod 954 to the sleeve 956 by tension applied through the spring 978. The means for controlling the dogs 960 remains in this condition 75 until the lasting operation is completed, the shoe

removed from the machine, another shoe placed in the jack and the jack moved to bring its ball 962 into engagement with the surface 964.

Formed upon the right-hand end of the rod 1006 are rack teeth 1012 meshing with the teeth 80 of a pinion 1014 fast upon a short shaft 1016 to which is also secured a pinion 1018 meshing with rack teeth formed upon a rod 1020. Movement of the rod 1006 to the right to operate the dogs 960 to latch the rod 954 to the sleeve 956 also causes a depression of the rod 1020, downward movement of which withdraws a locking bolt (not shown) with which the stop motion 454 is provided thereby permitting the clutch member 456 to move into driving contact with the clutch member 458 under the influence of a spring 1022 to start the machine.

90 The measuring means for positioning the presser feet

95

Except for small differences now to be described, the mechanism for positioning the presser feet 74 and 76 in accordance with the size of the shoe in the jack is substantially the same as similar mechanism shown and described in the prior Letters Patent No. 1,854,204 hereinbefore mentioned. As shown particularly in Fig. 4, the vertical shaft 1024, which corresponds to the shaft 948 of the machine shown in said Letters Patent, and the connections from said shaft to the lever 1464, which corresponds to the lever 464 of the machine of said Letters Patent, are located at the left-hand side of the head 52 of the machine instead of at the right-hand side as shown in said Letters Patent. Secured to the lower end 110 of the shaft 1024 is an arm 1026 connected by a link 1028 to a rod 1030 which is mounted for transverse sliding movement in the head 52 of the machine and which corresponds to the rod 938 shown in the machine of said Letters Patent No. 1,854,204. The rod 1030 carries a roll 1032 engaging a cam surface 1034 formed on the inner side face of a projection 1036 formed on one end of a lever 1038 fulcrumed at 1040 to the base 50 of the machine. The lever 1038 like the lever 120 926 of the machine of the above-mentioned Letters Patent No. 1,854,204 carries a roll 1042 engaging a slot in a plate 1044 secured to the feed lever 926. It will be understood that as the jack 58 is moved by the operator in a direction lengthwise of the shoe to bring the gage 962 into engagement with the surface 964, a swinging movement is imparted to the feed lever 936 through the link 940. This movement of the lever 1038 causes the lever 1038, by reason of the engagement of the roll 1042 with the slot in the plate 1044, to swing about its pivot 1040 and through the connections above-described to impart to the units 54 and 56 a movement toward or from each other to determine the positions of the units 130 widthwise of the machine in accordance with the size of the shoe in the jack. The presser feet 74 and 76 are thus positioned properly to engage the insole, between the ribs of the insole, as the jack is moved upwardly.

140

135 The operation of the machine

As the operation of the machine has already been described in detail in connection with the description of its construction, nothing more than 145 a very brief statement of its mode of operation is necessary at this point. Before the shoe is presented to this machine, it may have been and as illustrated has been previously lasted at its toe end. While the toe end lasting operation may 150

- be performed in any known or suitable manner, as illustrated it has been performed by the use of a machine such as that disclosed in a copending application Serial No. 671,664, filed May 18, 5 1933, in the name of E. A. Holmgren. The machine is organized to operate automatically when the treadle 994 is depressed, to cause the upper-tensioning and fastening-inserting units 54, 56 to operate through a predetermined number of 10 cycles. Each of the pairs of grippers 132 is caused to seize the shoe upper and pull it into lasted relation to the insole and last whereupon the wipers 162 of the carriers 150 wipe the upper inwardly over the feather and into engagement with the rib of the insole and a staple and a tack are inserted at each side of the shoe by the drivers 206, 304. The staples are inserted through the shoe upper and into the rib of the insole and are clenched upon the inner surface of the rib 15 against the clenching surfaces 268 of the presser feet 74, 76. The tacks are inserted through the upper in the angle between the feather and the rib of the insole into the insole and last close to the base of the rib and are deflected in curved 20 paths inwardly away from the edge of the last bottom by the deflecting surfaces 280. The jack 58 is fed step by step to the left between the successive upper-tensioning and fastening-inserting operations so that by the time the lasting is finished the tip line of the shoe in the jack 58 has 25 reached the upper-tensioning and fastening-inserting units 54, 56. From this position the jack 58 is depressed, swung outwardly and moved a single step to the right to bring it to the position which it occupies when the machine is at rest, the last pin 862 being moved rearwardly relatively to the toe rest 856 to release the shoe during movement of the jack into inoperative position. After this the machine comes entirely 30 to rest except for the driving motor, the clutch member 458 and a few parts associated therewith, and the operator removes the shoe. 35 Having thus described my invention, what I claim as new and desire to secure by Letters Patent of the United States is:—
1. A lasting machine having, in combination, progressively operating means for working a shoe upper over a last having a sole member positioned thereon, and means for progressively and substantially simultaneously securing opposite marginal portions of the shoe upper in lasted relation to the sole and last respectively by fastenings of different kinds. 40
2. A lasting machine having, in combination, progressively operating means for laying the opposite marginal portions of a shoe upper assembled on a last simultaneously over the bottom of a sole member positioned on the last, and means for progressively inserting metallic fastenings of different kinds in pairs through said opposite marginal portions substantially simultaneously to secure the upper in lasted relation to the last and sole. 45
3. A lasting machine having, in combination, means operating at opposite sides of a shoe simultaneously to work different portions of the shoe upper progressively over a last having an insole positioned thereon, and means for inserting staples and tacks through said portions into the insole to secure the upper permanently to the insole and temporarily to the last. 50
4. A lasting machine having, in combination, means operating at opposite sides of a shoe simultaneously to work different portions of the shoe upper progressively over a last having a ribbed 55
- insole positioned thereon, and means for securing said portions permanently to the insole by one kind of fastening inserted through the upper and the rib of the insole and temporarily to the last by another kind of fastening inserted through the upper and body of the insole into the last. 80
5. A side lasting machine having, in combination, means operating on a shoe upper simultaneously at opposite sides thereof between the heel breast line and the tip line to work the shoe upper over a last having a ribbed insole positioned thereon, and means for inserting different kinds of fastenings simultaneously through each of the opposite marginal portions of the shoe upper into the insole to secure the shoe upper in lasted relation to the insole and last. 85
6. A lasting machine having, in combination, means for working a shoe upper over a last having an insole positioned thereon, and means for inserting different kinds of fastenings in pairs at opposite marginal portions of the shank and ball portions of the shoe upper into the insole to secure the shoe upper in lasted relation to the last and insole. 90
7. A lasting machine having, in combination, means for working a shoe upper over a last having an insole positioned thereon, and means for inserting pairs of different kinds of fastenings substantially simultaneously through opposite marginal portions of the shoe upper and into the insole to secure the shoe upper in lasted relation to the insole and last. 95
8. A side-lasting machine having, in combination, means for working a shoe upper over a last having an insole positioned thereon, and two pairs of fastening-inserting mechanisms operating substantially simultaneously to insert different kinds of fastenings in pairs at opposite marginal portions of the shank and ball portions of the shoe upper into the insole to secure the shoe upper in lasted relation to the insole and last. 100
9. A side-lasting machine having, in combination, means for working a shoe upper over a last having an insole positioned thereon, and means for inserting separate metallic fastenings of different kinds substantially simultaneously through opposite marginal portions of the shoe upper into the insole to secure the shoe upper in lasted relation to the insole and last. 105
10. A side-lasting machine having, in combination, means for working opposite marginal portions of a shoe upper over a last having a ribbed insole positioned thereon, means for inserting fastenings through the opposite lasted portions of the upper while they are held in lasted position and into the rib of the insole to secure the upper permanently in lasted relation to the insole, and means operating substantially simultaneously with said last-named means for inserting different fastenings through the opposite marginal portions of the upper into the insole and last to secure the upper temporarily in lasted relation to the last. 110
11. A side-lasting machine having, in combination, means for working opposite marginal portions of a shoe upper over a last having a ribbed insole positioned thereon, means for inserting fastenings through the opposite lasted portions of the upper into the rib of the insole in directions inclined to the plane of the insole to secure the upper permanently in lasted relation to the insole, and means operating substantially simultaneously with said last-named means for inserting different fastenings through the opposite marginal portions of the upper into the insole and last. 115

last to secure the upper temporarily to the last.

12. A lasting machine having, in combination, means arranged to operate simultaneously along opposite sides of a shoe upper progressively from the vicinity of the heel-breast line to the vicinity of the tip line to work a shoe upper over a last having a ribbed insole positioned thereon, and means for inserting pairs of metallic fastenings of different kinds in directions at an angle to each other through opposite marginal portions of the shoe upper operating progressively with said upper working means to secure the upper permanently to the insole and temporarily to the last.

13. A lasting machine having, in combination, means arranged to operate simultaneously along opposite sides of a shoe upper progressively from the vicinity of the heel-breast line to the vicinity of the tip line to work a shoe upper over a last, and means for simultaneously inserting pairs of different kinds of metallic fastenings in convergent directions through opposite marginal portions of the shoe upper into the insole operating progressively with said upper working means to secure the upper permanently in lasted relation to the insole and temporarily in lasted relation to the last.

14. In a lasting machine, a work support, means for working opposite marginal portions of a shoe upper over a last carried by said support and having an insole positioned thereon, fastening-inserting means arranged to insert successively pairs of different kinds of metallic fastenings through opposite marginal portions of the shoe upper into the insole to secure the shoe upper in lasted relation to the insole and last, and automatically operating means for causing relative movement of the fastening-inserting means and the work support between the insertion of successive pairs of the different kinds of fastenings.

15. A lasting machine having, in combination, means including a pair of wipers operating on a shoe upper at opposite sides thereof to work the upper step by step over a last having a ribbed insole positioned thereon, and fastening-inserting means arranged to insert staples through opposite marginal portions of the shoe upper into the rib of the insole to secure the upper in lasted relation to the insole and substantially simultaneously therewith to insert different fastenings through the upper into the insole and last to secure the shoe upper temporarily in lasted relation to the last.

16. A side-lasting machine having, in combination, means operating at opposite sides of a shoe simultaneously to work different portions of the shoe upper progressively over a last having an insole positioned thereon, and staple inserting and tack-driving means operating progressively with said upper working means to insert staples and tacks through said opposite marginal portions to secure the upper in lasted relation to the insole and last.

17. In a lasting machine, a work-support, means for working a shoe upper over a last carried by said support and having an insole positioned thereon, staple-inserting means arranged to insert successively pairs of staples through opposite marginal portions of the shoe upper into the insole in directions inclined to the plane of the body of the insole, means for driving tacks in pairs through opposite marginal portions of the shoe upper into the insole and last, and automatically operating means for causing relative movement of the staple-inserting means, the tack

driving means and the work-support between the insertion of successive pairs of staples and tacks.

18. A lasting machine having, in combination, means including a pair of wipers for working opposite marginal portions of the shank and ball portion of a shoe upper over a last having an insole positioned thereon, and pairs of fastening-inserting mechanisms arranged to secure opposite lasted portions of the shoe upper permanently to the insole by one kind of fastening and temporarily to the last by another kind of fastening.

19. A side-lasting machine having, in combination, a pair of wipers arranged to engage opposite marginal portions of the shank and ball portions of a shoe upper to wipe the shoe upper over an insole positioned on a last, stapling means arranged to insert staples simultaneously through said portions of the shoe upper into the insole to secure the shoe upper permanently in lasted relation to the insole, and tack driving means operating substantially simultaneously with said stapling means for inserting tacks through the opposite marginal portions of the shoe upper into the insole and last to secure the shoe upper temporarily in lasted relation to the last.

20. A lasting machine, having in combination, upper-tensioning grippers arranged simultaneously to engage opposite marginal portions of a shoe upper and to stretch the shoe upper over a last having an insole positioned thereon, a pair of progressively-operating wipers adjacent to the grippers arranged to wipe the stretched upper over the margin of the insole, and progressively operating staple-inserting means and tack driving means arranged to insert staples and tacks in pairs through opposite marginal portions of a shoe upper into the insole and last to secure the shank and ball portions of the shoe upper in lasted relation to the insole and last.

21. A lasting machine having, in combination, a last support, means arranged to operate progressively along opposite sides of a shoe upper to work the shoe upper over a last carried by said support, staple inserting means and tack-driving means arranged to insert staples and tacks in pairs through opposite marginal portions of the upper into the insole and last to secure the upper in lasted relation to the last and insole, and mechanism for moving the last support step by step to feed the shoe upper and the insole on the last past the upper working means and the staple-inserting and tack-driving means and arranged to vary the extent of the feeding steps in accordance with the size of the last carried by the support.

22. A lasting machine having, in combination, a jack for supporting a last having an upper and a ribbed insole positioned thereon, and a pair of upper tensioning and fastening-inserting units comprising means for gripping opposite marginal portions of the upper and for tensioning the upper heightwise of the last, means for working said portions into the angle at the base of the rib and for clamping said portions against said rib, staple-inserting means arranged to secure said portions to the rib of the insole, and separate tacking means for securing the upper to the last to prevent displacement of the rib.

23. A lasting machine having, in combination, a jack arranged to support a last upon which are assembled a shoe upper and a ribbed insole, a pair of supports, a pair of progressively operating upper tensioning and fastening-inserting units rotatably mounted on said supports and ar-

- ranged to secure opposite marginal portions of the shoe upper permanently to the rib of the insole by one kind of fastening and temporarily to the last by another kind of fastening, said units having a pair of abutments for engaging the inner face of the rib of the insole at opposite sides of the shoe to position the shoe transversely of the machine, means for feeding the jack step-by-step past the units, and means for rotating the units relatively to their supports toward and from each other to maintain the angular relation of the units to the edge of the insole uniform as different portions of the shoe upper are operated upon. 80
- 15 24. A lasting machine having, in combination, a jack for supporting a last having a shoe upper and a ribbed insole assembled thereon, a pair of supports, upper tensioning and fastening inserting units rotatably mounted on said supports 85
- 20 operating progressively on opposite sides of the last to work opposite marginal portions of the shoe upper into lasted relation to the last and insole and to insert a plurality of metallic fastenings of different kinds through said opposite 90
- 25 marginal portions to secure the upper in lasted relation to the last and insole, feeding means for the jack arranged to move the jack step-by-step past the units, and means operating in timed relation to said jack feeding means for turning 95
- 30 the units relatively to the supports to maintain the relation of the units to the edge of the insole uniform as the point of operation of the units is transferred along the shoe. 100
25. A lasting machine having, in combination, a jack for supporting a last having a shoe upper and a ribbed insole assembled thereon, and a pair of upper tensioning and fastening-inserting units comprising means for gripping opposite marginal portions of the shoe upper and for tensioning said 105
- 40 portions about the last, means for working said portions inwardly over the bottom of the last into the angle at the base of the rib of the insole and to clamp said portions against the rib of the insole, staple-inserting means arranged to insert 110
- 45 staples through the clamped upper and the rib of the insole to secure the upper permanently to the rib of the insole, and separate tacking means arranged to secure the upper temporarily to the last to prevent displacement of the rib by tacks 115
- 50 inserted through the upper and insole and into the last at the base of the rib. 120
26. A lasting machine having, in combination, a support for a last having a shoe upper and a ribbed insole positioned thereon, and a pair of upper tensioning and fastening-inserting units comprising means for gripping the upper at opposite sides of the shoe and for tensioning the upper about the last, slides movable inwardly over the bottom of the last at an angle to the 125
- 60 bottom of the insole to work the upper into the angle at the base of the rib and to clamp the upper against the rib, staple-inserting means arranged to insert staples through the upper and the rib of the insole, and separate tack-driving means arranged to insert tacks through the upper and the insole at the base of the rib. 130
27. A lasting machine having, in combination, a jack for supporting a last having a shoe upper and a ribbed insole assembled thereon, and a pair of upper tensioning and fastening-inserting units operating at opposite sides of the shoe comprising wipers movable inwardly over the shoe bottom to wipe opposite marginal portions of the shoe upper over the margin and into engagement with the 135
- 70 rib of the insole, staple-inserting means movable 140
- 75 in the same direction as the wiping means to insert staples through the upper and rib of the insole, and tack-driving means arranged to drive tacks through the upper and insole and into the last at an angle to the wiping means. 145
28. A lasting machine having, in combination, a work support for a last having a shoe upper and a ribbed insole assembled thereon and a pair of upper tensioning and fastening-inserting units operating at opposite sides of the shoe to secure opposite marginal portions of the upper in lasted relation to the insole and last comprising wipers movable inwardly over the shoe bottom to wipe opposite marginal portions of the shoe upper over the margin and into engagement with the rib of the insole, staple-inserting means movable in the same direction as the wiping means to insert staples through the upper and the rib of the insole to secure the upper in lasted relation to the insole, and tacking means arranged to insert tacks through the upper and insole and into the last in predetermined relation to the staple-inserting means. 150
29. A lasting machine having, in combination, means for supporting a last having a shoe upper and a ribbed insole positioned thereon, and a pair of upper tensioning and fastening-inserting units operating at opposite sides of the shoe upper to work opposite marginal portions of the shoe upper over the margin and into engagement with the rib of the insole and to secure said opposite marginal portions permanently to the insole and temporarily to the last by metallic fastenings of different kinds said units having staple-inserting and tack-driving means, and wiping means arranged to cooperate with the staple-inserting and tack-driving means to cause the fastenings to be inserted in predetermined relation to the rib of the insole. 110
30. A lasting machine having, in combination, a jack for supporting a last having a shoe upper and a sole member positioned thereon, means for imparting a plurality of feeding movements to the jack in the direction of the length of the shoe supported thereby, and a pair of upper tensioning and fastening inserting units operating progressively on opposite sides of the shoe to work opposite marginal portions of the upper over the margin of the sole and to secure said portions in lasted relation to the sole and last by fastenings of different kinds, said units comprising a pair of grippers for tensioning the upper heightwise of the last, a pair of wipers for laying the opposite marginal portions of the tensioned upper inwardly over the bottom of the sole, and two pairs of fastening inserting mechanisms operating simultaneously at opposite sides of the shoe to insert staples and tacks through the opposite overlaid portions of the upper into the insole and last respectively. 120
31. A lasting machine having, in combination, a jack for supporting a last having a shoe upper and a ribbed insole positioned thereon, means for feeding the jack step-by-step in the direction of the length of the shoe supported by the jack, said means being arranged to vary the length of the feeding movements of the jack in accordance with the size of the shoe supported thereby, and a pair of upper tensioning and fastening inserting units each comprising a gripper for tensioning the marginal portion of the upper over the last, a pair of slides normally held in withdrawn position above the bottom of the insole during movement of the jack to feed the shoe but movable toward the bottom of the shoe between successive feeding 135
- 140
- 145
- 150

movements of the jack, one of said slides having a surface formed and arranged to wipe the tensioned margin of the upper over the bottom of the insole into engagement with the rib and carrying 5 also a nozzle for directing a fastening through the upper and the rib of the insole and the other of said slides being arranged to move a fastening guiding nozzle into position for directing a fastening through the upper and insole and into the 10 last at the base of the rib, and a pair of drivers for the fastenings normally held in retracted position during movement of the slides toward the work but independently operative to insert the fastenings after the slides have completed their 15 movements toward the work.

32. A lasting machine having, in combination, wipers operating at opposite sides of a shoe simultaneously to work different portions of the shoe upper progressively over a last having an 20 insole positioned thereon, staple-inserting means arranged to insert staples simultaneously through said opposite marginal portions to secure the upper to the rib of the insole, separate tack-driving means comprising tack-carrying slides movable toward the bottom of the shoe in response to 25 inward movement of the wiping means to position the tacks in close relation to the rib of the insole; and means for driving the tacks through the upper and insole and into the last.

33. A lasting machine having, in combination, a pair of wipers operating at opposite sides of a shoe simultaneously to work different portions of the shoe upper progressively over a last having a 30 ribbed insole positioned thereon, and staple inserting and tack driving means operating progressively with said wiping means to insert staples and tacks through said opposite marginal portions to secure the upper in lasted relation to the insole and last, said wipers having nose portions 35 arranged to cooperate with the tack-driving means to deflect the tacks in paths curved transversely of the rib of the insole.

34. A lasting machine having, in combination, a pair of wipers operating at opposite sides of a 40 shoe simultaneously to work different portions of the shoe upper progressively over a last having an insole positioned thereon, and staple-inserting and tack-driving means operating progressively with said upper working means to insert staples and tacks through said opposite marginal portions to secure the upper in lasted relation to the 45 insole and last, said wipers having nose portions formed and arranged to bend the tacks before they are inserted in the shoe in directions transversely of the line of drive of the tacking means.

35. A lasting machine having, in combination, a pair of wipers operating at opposite sides of a shoe simultaneously to work different portions of a shoe upper progressively over a last having an 50 insole positioned thereon, a pair of fastening inserting drivers operating progressively with said upper working means to insert fastenings simultaneously through said opposite marginal portions to secure the upper in lasted relation to the insole and last, and means movable with said wipers for limiting the operative movement of the 55 drivers.

36. A lasting machine having, in combination, a jack for supporting a last having a shoe upper 60 and a ribbed insole assembled thereon, a pair of anvils for engaging the inner surfaces of the rib of the insole at opposite sides of the shoe, gripper means for engaging the shoe upper simultaneously at opposite sides of the shoe and arranged 65 to tension the upper about the last, and fasten-

ing-inserting means constructed and arranged to insert a plurality of different fastenings at opposite sides of the shoe comprising slides movable toward the anvils to work the tensioned upper into the angle at the base of the rib and to cooperate in the insertion of the fastenings while the upper is held in said position.

37. A lasting machine having, in combination, a jack for supporting a last having a shoe upper and a ribbed insole assembled thereon, a pair of anvils for engaging the rib at opposite sides of the shoe to position the shoe transversely of the machine, grippers for engaging the shoe upper simultaneously at opposite sides of the shoe to tension the upper heightwise of the last, and fastening-inserting means arranged to insert a plurality of fastenings of different kinds at opposite sides of the shoe comprising slides movable toward the anvils to work the upper into the angle at the base of the rib of the insole and to clamp the upper against said rib while a fastening is being inserted to secure the upper permanently to the insole and to bend opposite portions of the upper and rib inwardly toward the bottom surface of the shoe while fastenings are being inserted at the base of the rib to secure the upper temporarily to the last.

38. A lasting machine having, in combination, a support for a last having a shoe upper and a ribbed insole assembled thereon, a pair of anvils for engaging the rib of the insole at opposite sides of the shoe, progressively operating gripper means arranged to engage opposite marginal portions of the shoe upper and to tension the upper heightwise of the last, and progressively operating fastening-inserting means arranged to insert fastenings of different kinds in pairs through said opposite marginal portions to secure the upper in lasted relation to the insole and last, said last-named means having slides movable inwardly over the bottom surface of the shoe to work the tensioned upper into the angle at the base of the rib, said slides being arranged to clamp the upper and the rib against the anvils while fastenings are being inserted to secure the upper to the rib of the insole and to bend opposite marginal portions of the upper and the rib rearwardly of the anvils at an angle to the bottom of the insole while fastenings are being inserted to secure the upper to the last.

39. A lasting machine having, in combination, a support for a last having a shoe upper and a ribbed insole positioned thereon, a pair of anvils for engaging the inner surfaces of the rib of the insole at opposite sides of the shoe, gripper means for tensioning the upper at opposite sides of the shoe, and fastening inserting means comprising slides movable toward the anvils to work the tensioned upper at opposite sides of the shoe into the angle at the base of the rib of the insole and to clamp the upper against the rib of the insole, said slides having nose portions the work engaging surfaces of which are formed at an angle to the surface of the insole to bend opposite portions of the upper and rib inwardly rearwardly of the anvils, means for inserting staples through the clamped upper and insole arranged to clinch the legs of the staples against the anvils to secure the upper in lasted relation to the insole, and means for inserting tacks through the inwardly bent portion of the upper into the insole and last to secure the upper temporarily in lasted relation to the last.

40. A lasting machine having, in combination, means including a pair of wipers operating on a

- shoe upper at opposite sides thereof to work the upper progressively over a last having a ribbed insole thereon, a pair of staple guiding nozzles movable with said wipers inwardly over the bottom of the shoe into position for fastening the upper to the rib of the insole, tack carrying slides movable toward the bottom of the shoe in response to inward movement of the wipers, staple inserting means comprising drivers movable relatively to the wipers to insert staples through the upper and the rib of the insole, tack driving means comprising drivers movable relatively to the slides for inserting tacks through the upper and insole and into the last, spring operated means for imparting operative movement to the drivers, and means for releasing said last-named means to effect simultaneous insertion of the staples and tacks. 41. A lasting machine having, in combination, means including a pair of wipers operating on a shoe upper at opposite sides thereof to work the upper step-by-step over a last having a ribbed insole thereon, a pair of staple guiding nozzles movable with said wipers inwardly over the bottom of the shoe into position for fastening the upper to the rib of the insole, tack carrying slides movable toward the overlaid portions of the upper in response to inward movement of the wipers, staple-inserting means comprising drivers movable relatively to the wipers to insert staples through the upper and the rib of the insole, tack-inserting means comprising drivers movable relatively to the slides for inserting tacks through the upper and insole and into the last, spring operated levers for imparting operative movement to the drivers, and means for releasing said levers to effect simultaneous insertion of the staples and tacks. 42. A lasting machine having, in combination, an abutment arranged to engage the inner surface of the rib of an insole positioned on a last having a shoe upper assembled thereon, means for pulling the upper over the last, a member for guiding fastenings arranged to engage the tensioned marginal portion of the upper and to move inwardly toward the rib of the insole in a direction inclined to the plane of the insole to press the upper against the rib and to bend the upper and the rib adjacent to the abutment toward the bottom surface of the insole, said member having a pair of guideways formed therein one of which is arranged to direct a fastening through the upper and the rib of the insole and the other of which is arranged to direct a different fastening through the upper and insole into the last at the base of the rib, and means for driving fastenings through said guideways to secure the upper to the last and insole. 43. A lasting machine having, in combination, a pair of wipers operating at opposite sides of a shoe simultaneously to work different portions of the upper progressively over a last having a ribbed insole positioned thereon, staple inserting means arranged to insert staples through said opposite marginal portions to secure the upper permanently in lasted relation to the insole, tack driving means arranged to insert tacks through the upper and insole into the last to secure the upper temporarily in lasted relation to the last, and tack deflecting means carried by the wipers and arranged to cooperate with the tack driving means to deflect the tacks in curved paths inwardly toward the body portion of the last. 44. A lasting machine having, in combination, a pair of wipers operating at opposite sides of a shoe to work opposite marginal portions of the shoe upper simultaneously over a last having a ribbed insole positioned thereon, staple-inserting means arranged to insert staples simultaneously through said marginal portions to secure the upper permanently to the rib of the insole, means operating substantially simultaneously with the staple-inserting means to insert tacks through the upper and insole and into the last at opposite sides of the shoe to secure the upper temporarily in lasted relation to the last, said wipers having nose portions to press the upper and insole inwardly at an angle to the plane of the bottom of the shoe and having also guideways in said nose portions for directing the tacks through the inwardly bent portions of the upper and the insole at the base of the rib. 45. A lasting machine having, in combination, a wiper arranged to work different portions of a shoe upper progressively over a last having an insole positioned thereon, a fastening inserting driver operating progressively with said upper working means to insert fastenings through the marginal portion of the upper into the insole to secure the upper in lasted relation to the insole and last, a spring operated lever for imparting operative movement to the driver, and a stop carried by the wiper for limiting the movement of the driver. 46. A lasting machine having, in combination, a wiper arranged to wipe the marginal portion of a shoe upper over a last having a sole member positioned thereon, a fastening-inserting driver arranged to insert a fastening through said marginal portion to secure the upper in lasted relation to the sole, a spring operated lever for imparting operative movement to the driver and a second lever connected to the wiper and movable therewith for limiting movement of the first lever. 47. A lasting machine having, in combination, grippers arranged simultaneously to engage opposite marginal portions of a shoe upper to stretch the shoe upper over a last having a ribbed insole positioned thereon, a pair of slides movable toward and from the work and having staple-guiding nozzles, wipers carried by the slides, staple forming means comprising inside formers and outside formers movable relatively to the inside formers to form staples from pieces of wire presented thereto and then to move the slides toward the work to cause the wipers to wipe the opposite marginal portions of the tensioned upper over the margin of the insole into engagement with the rib and to move the nozzles into position for directing staples through the opposite marginal portions of the upper and the rib of the insole, and means for inserting the staples after the slides have completed their movement toward the work. 48. A lasting machine having, in combination, a slide, a fastening guiding nozzle and a wiper carried by said slide, a second slide, an outside former carried by said second slide, a lever, an inside former carried by said lever, means for moving said second slide and said outside former relatively to said inside former to form a staple from a piece of wire presented thereto and then to move said first-named slide toward the work to cause the wiper to wipe a portion of a shoe upper into lasted position and to position said nozzle in engagement with the work, and means for driving the staple through said nozzle to secure the upper in lasted position. 49. A lasting machine having, in combination, a slide, a throat member provided with a driver passage and a wiper carried by said slide, a second

slide having a driver passage formed therein in alignment with the driver passage formed in said throat member, an outside former carried by said second slide, a lever, an inside former carried by said lever, means for moving said second slide relatively to said first slide to cause the outside former to form a staple around the inside former and then to move into engagement with said throat member to form a continuous passage for the staple after which, during continued movement of said second slide, said first slide is moved toward the work to cause the wiper to wipe a portion of a shoe upper into lasted position and to position the throat member in engagement with the work, a fastening inserting driver mounted for movement through said driver passage, and means for operating the driver to insert a staple to secure the upper in lasted position.

50. A lasting machine having, in combination, a slide, a throat member having a driver passage therein and a wiper carried by said slide, a second slide having a driver passage formed therein in alignment with the passage formed in said throat member, an outside former carried by said second slide, a third slide having a driver mounted for movement in said driver passages, a lever, an inside former carried by said lever, means for moving said second slide relative to said first slide to cause the outside former to form a staple around the inside former from a piece of wire presented thereto and then to move into engagement with said throat member to form a continuous passage for the staple after which, during continued movement of said second slide, said first slide is moved toward the work to cause the wiper to wipe a portion of a shoe upper into lasted position and to position the throat member in engagement with the work, and means for moving the third slide relative to the first slide to cause the driver to move through the driver passage to insert a staple to secure the upper in lasted position.

51. A lasting machine having, in combination, means for shaping a shoe upper over a last, means for driving a fastening through the upper into the last, and means for engaging the fastening before it enters the shoe and during the driving operation to deflect it in a curved path.

52. A lasting machine having, in combination, means for forming an upper over a last, means for inserting fastenings through the upper into the last, and means for engaging the fastenings before they enter the shoe to deflect them in curved paths inwardly away from the edge of the last bottom.

53. A lasting machine having, in combination, means for working the marginal portion of a shoe upper over a last having a sole member positioned thereon, means for inserting fastenings through the upper and sole member and into the last, and a member in the line of drive of the fastenings for bending them during the driving operation to cause them to enter the last in curved paths.

54. A lasting machine having, in combination, means for tensioning an upper over a last, means for driving a tack through the tensioned upper into the last, and a deflector arranged to engage the tack before it enters the shoe to deflect it in a curved path inwardly toward the body portion of the last.

55. A lasting machine having, in combination, means for shaping an upper over a last, means for driving a tack through the upper into the last, and means for engaging the tack before it enters the shoe and during the driving operation to bend

successive portions of it to cause the tack to enter the last in a curved path.

56. A lasting machine having, in combination, means for working the marginal portion of a shoe upper over a last, tack driving means arranged to insert a tack through the shoe upper into the last, and a deflector for engaging the tack before it enters the shoe to deflect it in a curved path inwardly away from the edge of the last bottom.

57. A lasting machine having, in combination, means including a wiper for working the marginal portion of a shoe upper over a sole member positioned on a last, means for driving a tack through the upper and the sole member into the last, and a device for engaging the tack before it enters the shoe and for bending it progressively in the driving operation to anchor it in the last.

58. A lasting machine having, in combination, means operating on a shoe upper simultaneously at opposite sides thereof to tension the upper heightwise of a last having a ribbed insole thereon, a pair of wipers operating simultaneously at opposite sides of the shoe to work the marginal portions of the tensioned upper into the angle at the base of the rib of the insole, and tack driving means operating simultaneously to insert tacks through the opposite marginal portions of the upper and the body of the insole into the last to secure the upper in lasted relation to the insole and last.

59. A lasting machine having, in combination, means for engaging the inner face of the rib of an insole positioned upon a last at points upon opposite marginal portions of the insole, progressively operating means for stretching opposite sides of a shoe upper over the last simultaneously, and progressively operating means for driving tacks simultaneously through said marginal portions into the insole and last to secure the upper in lasted relation to the last and insole.

60. A side lasting machine having, in combination, grippers arranged progressively to engage opposite marginal portions of a shoe upper and to stretch the shoe upper progressively over a last having a sole member positioned thereon, progressively operating wipers arranged to lay the opposite marginal portions of the tensioned upper inwardly over the bottom of the sole member, and means for inserting tacks simultaneously through said opposite marginal portions to secure the upper in lasted relation to the sole and the last.

61. A lasting machine having, in combination, means operating at opposite sides of a shoe upper simultaneously to tension the upper about a last and to wipe the opposite marginal portions of the upper inwardly over the edge of a ribbed insole member positioned on the last, and means for inserting tacks simultaneously through the opposite overwiped portions of the upper into the sole member and the last at the base of the rib to hold the opposite overwiped portions of the upper flat upon the feather of the insole.

62. A lasting machine having, in combination, a support, means including a pair of wipers arranged to operate progressively and simultaneously along opposite sides of a shoe upper to work the shoe upper over a last carried by said support and having an insole positioned thereon, means for simultaneously inserting tacks through said opposite marginal portions into the insole and last to secure the upper in lasted relation to the last and insole, and means for moving the support step by step to feed the shoe upper and the insole on the last past the upper working means and the tack driving means and arranged

- to vary the extent of the feeding movements of the support in accordance with the size of the last carried by the support.
63. A lasting machine having, in combination, 5 a pair of wipers operating at opposite sides of the shoe simultaneously to work different portions of the shoe upper over a last having a ribbed insole positioned thereon, a pair of slides operating simultaneously with said wipers to 10 position fastenings for insertion into the work in predetermined relation to the rib of the insole, and means operating substantially simultaneously to insert the fastenings after the slides have completed their movements toward the 15 work.
64. A lasting machine having, in combination, a pair of grippers arranged to grip the opposite marginal portions of the shoe upper mounted on a last and to tension the upper heightwise of 20 the last, a pair of wipers, a pair of slides for moving said wipers inwardly at an angle to the bottom of the last to work the opposite marginal portions of the tensioned shoe upper into the angle at the base of the rib of a sole member 25 positioned on the last, a second pair of slides movable toward the bottom of the last in response to inward movement of the first-named slides to position fastenings in predetermined relation to the rib of the sole member, a pair of 30 spring operated drivers for the fastenings, and means for releasing the drivers to insert the fastenings after the slides have completed their movement toward the work.
65. A lasting machine having, in combination, 35 a gripper for tensioning a shoe upper over a last, a wiper for wiping the tensioned upper inwardly over the bottom of a sole member positioned on the last, a tack carrying slide mounted independently of the wiper and movable toward the bottom of the shoe in response to inward movement of the wiper, and means for inserting a tack through the upper and the sole member and into the last.
66. A lasting machine having, in combination, 45 an abutment for engaging the bottom of a sole member assembled upon a last, a wiper movable to lay the marginal portion of a shoe upper assembled on the last over the bottom of the sole, a tack guiding nozzle movable toward the bottom of the shoe in a different direction than the wiper in response to inward movement of the wiper, and a driver for driving a tack from said nozzle to fasten the upper to the sole on the last.
67. A lasting machine having, in combination, 55 an abutment for engaging the bottom of a sole member assembled on a last, a wiper movable inwardly at an angle to the bottom of a last to lay the marginal portion of a shoe upper assembled on the last over the edge of the sole, a tack guiding nozzle, a slide arranged to move said nozzle toward the work in response to inward movement of the wiper, and a driver for driving a tack from said nozzle to fasten the upper to the sole.
68. A lasting machine having, in combination, 60 means for pulling an upper over a last, a wiper movable to lay the tensioned marginal portion of the upper over a sole member on the last, a tack guiding nozzle movable toward the bottom of the shoe in response to inward movement of the wiper, a driver for driving a tack from said nozzle to fasten the upper to a sole, and a deflector movable with the wiper and arranged to engage the tack before it enters the shoe to 65
- deflect it in a curved path such as to anchor it in the last.
69. A lasting machine having, in combination, a pair of grippers operating simultaneously to grip and tension the opposite marginal portions of a shoe upper over a last having a ribbed insole positioned thereon, two pairs of slides operating simultaneously on opposite sides of the shoe to lay the tensioned marginal portion of the upper over the feather and into engagement with the rib of the insole and to position fastenings for insertion through said overlayed marginal portions into the insole and last at the base of the rib, and means for inserting the fastenings. 70. A lasting machine having, in combination, 80 means for tensioning the opposite marginal portions of a shoe upper over a last having a ribbed insole positioned thereon, two pairs of slides movable in converging directions at opposite sides of the shoe to work the marginal portions of the upper into the angle at the base of the rib and to position fastenings for insertion through said overworked marginal portion into the insole and last at the base of the rib, and means operating 85 simultaneously to insert the fastenings after the slides have completed their movement toward the work.
71. A lasting machine having, in combination, upper wiping mechanism and upper tacking mechanism including a wiper and a tack carrying 90 nozzle both normally held in withdrawn position above the bottom of the shoe but movable simultaneously toward the shoe to wipe the marginal portion of a shoe upper over the bottom of a ribbed insole positioned on a last and to position a tack for insertion through the overworked 95 portion of the upper and the insole at the base of the rib, and means for inserting the tack.
72. A lasting machine having, in combination, upper tacking means, means including a wiper 100 for working the marginal portion of the shoe upper over the bottom of a last having a ribbed insole positioned thereon, said wiper having a nose portion formed and arranged to bend the surplus portion of the upper and the rib of the insole 105 inwardly at an angle to the line of drive of the tacking means and having also a guideway formed in said nose portion for directing a tack through the upper and insole and into the last at the base of the rib, and means for operating the 110 tacking means to insert a tack through said guideway.
73. A lasting machine having, in combination, 115 means including a pair of wipers for working the opposite marginal portions of a shoe upper into the angle at the base of the rib of an insole positioned on a last, said wipers having guideways formed therein for directing fastenings through the upper and insole and into the last at the base of the rib, and means for inserting fastenings through said guideways. 120
74. A lasting machine having, in combination, a support for a last having a shoe upper and an insole positioned thereon, gripping mechanism cooperating with said support to tension the upper about the last, means for feeding the support step by step past the gripping mechanism, and means operating in timed relation to said feeding means for rendering said gripping mechanism inoperative. 125
75. A lasting machine having, in combination, a support for a last having a shoe upper and a sole member assembled thereon, lasting units including upper tensioning devices arranged to tension a shoe upper heightwise of a last carried by 130

said support, means for operating said upper tensioning devices to stretch the upper progressively over the last as the point of operation of said devices is transferred along the shoe, and 5 means for rendering said upper tensioning devices inoperative when some portions of the upper are being operated upon.

76. A lasting machine having, in combination, a support for a last having a shoe upper and a 10 sole member positioned thereon, fastening means, an upper tensioning gripper, means for feeding the jack step by step past the upper tensioning gripper and the fastening means, operating means for the gripper arranged to move the gripper 15 heightwise of the last carried by the support to tension a portion of the shoe upper about the last and then to lower the gripper into position for gripping a further portion of the upper after the tensioned portion of the upper has been secured in lasted position by the fastening means, and means operating in time with the last-named 20 means for rendering said means inoperative to lower the gripper at a predetermined time in the operation of lasting the shoe whereby said gripper is held in an out of the way position during 25 movement of the support to present previously tensioned portions of the shoe upper to the fastening means.

77. A lasting machine having, in combination, 30 a support for a last having a shoe upper and a sole member assembled thereon, lasting units including upper tensioning grippers arranged to tension a shoe upper over a last carried by the support and fastening inserting means arranged to insert fastenings through the tensioned upper 35 into the sole member to secure the upper in lasted relation to the sole and last, means for feeding the support step by step past the lasting units, operating means for the grippers constructed and arranged to move the grippers heightwise of the 40 last to tension opposite portions of the shoe upper over the last and then to move the grippers into position to grip successive portions of the shoe upper after the tensioned portions of the upper have been secured in lasted relation by the 45 fastening inserting means, and means operating in time with said last-named means for rendering said means inoperative to lower the grippers when portions of the shoe upper which have been previously tensioned are presented to 50 the fastening inserting means.

78. A lasting machine having, in combination, 55 a support for a last, lasting units including upper tensioning grippers operating on opposite sides of a shoe upper to tension the upper heightwise of a last carried by said support, means for feeding the support progressively past the lasting units to transfer the point of operation of the grippers along the shoe upper, and means operating in 60 timed relation to said feeding means for rendering said gripping means inoperative when predetermined portions of the shoe upper are operated upon.

79. A lasting machine having, in combination, 65 a jack for supporting a last having a shoe upper and an insole assembled thereon, upper tensioning and fastening-inserting units operating on opposite sides of the shoe upper simultaneously to work opposite marginal portions of the upper 70 over the insole and to secure said opposite marginal portions in lasted relation to the insole and last, means for feeding the support step by step past the upper tensioning and fastening-inserting units, upper tensioning grippers carried 75 by said units, means for imparting heightwise

movements to the grippers to tension the upper about the last as the point of operation of the grippers is transferred along the shoe, and mechanism operating in timed relation to the relative movements of the support and the units for rendering the grippers inoperative when some portions of the shoe upper are being operated upon and operative when other portions of the shoe upper are being operated upon.

80. A lasting machine having, in combination, 80 a work support arranged to carry a last having an insole and a shoe upper assembled thereon, a pair of gripper mechanisms arranged to engage the marginal portions of the shoe upper at opposite sides of the last, cyclically operating means for moving the gripper mechanisms away from the last to stretch the shoe upper over the last, a pair of cyclically operating fastening-inserting mechanisms arranged to insert fastenings 90 through the marginal portion of the stretched shoe upper into the insole and last, and means for rendering the gripper mechanisms inoperative during predetermined cycles of operation of the fastening-inserting means.

81. A lasting machine having, in combination, 100 a jack for supporting a last having an insole and a shoe upper assembled thereon, a pair of gripper mechanisms arranged to engage the marginal portion of a shoe upper at opposite sides of the last, cyclically operating means for moving the 105 gripper mechanisms away from the last to stretch the shoe upper over the last, means for feeding the jack step by step past the gripper mechanisms, and means for rendering the gripper mechanisms inoperative between predetermined feed- 110 ing movements of the jack.

82. A lasting machine having, in combination, 115 a jack for supporting a last having a shoe upper and an insole assembled thereon, a pair of gripper mechanisms arranged to engage the marginal portions of the shoe upper at opposite sides of the last, means for feeding the jack step by step past the gripper mechanisms to present different portions of the shoe upper to be operated upon, cyclically operated means for the grippers 120 arranged to move the grippers heightwise of the last to stretch the shoe upper over the last between successive feeding movements of the jack, and means operating in timed relation to the gripper operating means to prevent descent of 125 the grippers between predetermined feeding movements of the jack.

83. A lasting machine having, in combination, 130 a jack for supporting a last upon which are assembled a shoe upper and an insole, a pair of gripper mechanisms arranged to engage the marginal portions of a shoe upper at opposite sides of the last, cyclically operating means for moving the gripper mechanisms heightwise of the last to stretch the shoe upper over the last and 135 to return the gripper mechanisms to their lowermost positions, a pair of cyclically operating fastening inserting mechanisms arranged to insert fastenings through the marginal portions of the upper into the insole and last, means for 140 feeding the jack step by step past the gripper mechanisms and the fastening inserting mechanisms to present different portions of the shoe upper to be operated upon, and means acting automatically to prevent descent of the grippers 145 when predetermined portions of the shoe upper are presented to the fastening inserting mechanisms.

84. A lasting machine having, in combination, 150 a jack for supporting a last having a shoe upper

- and an insole positioned thereon, upper tensioning and fastening-inserting units, means for feeding the jack step by step past said upper tensioning and fastening-inserting units to pre- 5 sent different portions of the shoe upper to be operated upon, gripping mechanisms carried by the units and arranged to engage opposite marginal portions of the shoe upper and to tension the shoe upper heightwise of the last between successive movements of the last support, and means operating automatically at the end of predetermined upper tensioning operations to render said gripping mechanisms inoperative. 10 85. A lasting machine having, in combination, a jack, a pair of gripper mechanisms arranged to engage opposite marginal portions of a shoe upper held in assembled relation to a last upon said jack and to an insole on the last, operating means therefor arranged to impart heightwise movement to the gripper mechanisms to stretch the opposite marginal portions of the shoe upper over the last and to return the gripper mechanisms to their lowermost positions preparatory to tensioning successive portions of the shoe upper, means for feeding the last step by step past the gripper mechanisms, and means for rendering the gripper operating means inoperative to return the gripper mechanisms to their lowermost position between predetermined feed- 20 25 30 35 40 45 50 55 60 65 70 75
86. A lasting machine having, in combination, a jack arranged to support a last having a shoe upper and a sole member assembled thereon, a pair of grippers arranged to engage the marginal portions of the upper at opposite sides of the last, gripper operating means including a spring for imparting a yielding pull to the upper, and means becoming effective during the pull for rendering the pull positive upon compression of the spring. 87. A lasting machine having, in combination, a support for a last, a pair of grippers arranged to engage the opposite marginal portions of a shoe upper to stretch the upper about a last carried by the jack, means including a spring for operating the grippers to apply a yielding pull to the upper, and means operative upon yielding of the spring to cause the operating means to apply a positive pull to the upper. 88. A lasting machine having, in combination, a support for a last, a pair of grippers arranged to engage the opposite marginal portions of a shoe upper to stretch the upper about a last carried by the support, gripper operating mechanism including a spring for imparting a yielding pull to the upper, and adjustable means becoming effective during the pull for rendering the pull positive after a predetermined distortion has been imparted to the spring. 89. A lasting machine having, in combination, an abutment arranged to engage a ribbed insole positioned upon a last, a gripper arranged to engage the marginal portions of a shoe upper assembled on the last, means for operating the gripper including a spring to impart a yielding pull to the upper, and adjustable means operative upon distortion of the spring to render the pull positive to carry the gripper above the rib of the insole. 90. A lasting machine having, in combination, an abutment arranged to engage an insole positioned upon a last, a gripper arranged to engage the marginal portions of a shoe upper assembled on a last, gripper operating means including a 95 100 105 110 115 120 125 130 135 140 145 150
- spring for imparting a yielding pull to the upper, and an adjustable stop for limiting the yielding quality of the pull to increase the movement of the gripper away from the sole. 91. A lasting machine having, in combination, a support for a last having a shoe upper and a ribbed insole assembled thereon, a pair of grippers arranged to engage the edge of the shoe upper at opposite sides of the last, and means for imparting an impositive heightwise movement of the gripper to tension the shoe upper about the last, said means being arranged to cause a positive heightwise movement to be imparted to the grippers when the extent of their impositive movement is insufficient to carry the grippers above the rib of the insole. 92. A lasting machine having, in combination, an abutment arranged to engage an insole positioned on a last, a gripper arranged to engage the marginal portions of a shoe upper assembled on the last, means for operating the grippers to stretch the shoe upper over the last including a pair of springs operating alternatively to vary the stretching force applied to different portions of the upper by the grippers, and means becoming effective upon yielding of the springs to cause a portion of the pull to be positively effected. 93. A lasting machine having, in combination, means for working the marginal portions of a shoe upper over a last having a sole member positioned thereon including a wiper movable inwardly over the bottom of the last, a gripper for engaging the marginal portion of the upper, and means for operating the gripper to impart a yielding updraw movement to the gripper and then to impart a positive updraw movement to the gripper when the extent of the yielding updraw movement of the gripper is insufficient to move the gripper out of the path of the wiper. 94. A lasting machine having, in combination, a jack for supporting a last having a shoe upper and a ribbed insole thereon, a pair of grippers for engaging the upper at opposite sides of a shoe, cam operated means for the grippers including a spring arranged to cause a yielding pull to be applied to the upper, and means operative to cause a positive pull to be applied to the upper after the spring has been distorted a predetermined amount. 95. A lasting machine having, in combination, a support for a last having a shoe upper and a sole member assembled thereon, a pair of grippers arranged to engage the upper at opposite sides of the shoe, means including a spring for moving the grippers heightwise of the last to apply a yielding pull to the upper, and means operative upon yielding of the spring to cause a positive heightwise movement to be imparted to the grippers. 96. A lasting machine having, in combination, a work support arranged to carry a last having a ribbed insole and a shoe upper assembled upon it, a pair of gripper mechanisms adjustable to engage the edge of the upper at opposite sides of the last in predetermined relation to the bottom surface of the insole, means for causing relative movement of the work support and the gripper mechanisms lengthwise of the last to cause the gripper mechanisms to operate progressively along the shoe upper, and means for moving the gripper mechanisms heightwise of the last toward and from the edge of the shoe upper to cause the gripper mechanisms to stretch the upper progressively over the last arranged to maintain the limit of movement of the gripper

mechanisms away from the insole and shoe upper at a greater height than that of the top of the rib of the insole regardless of the point relative to the insole at which the grippers engage the upper.

97. A lasting machine having, in combination, a work support arranged to support a last having a shoe upper and a ribbed insole assembled upon it, a pair of gripper mechanisms arranged to engage the marginal portions of the shoe upper on opposite sides of the last, means for causing relative movement of the work support and the gripper mechanisms lengthwise of a shoe carried by the work support to cause the gripper mechanisms to operate progressively along the shoe upper, cyclically operating means for moving the gripper mechanisms heightwise of the last to cause the gripper mechanisms to stretch the shoe upper progressively over the last arranged to maintain the upper limit of movement of the gripper mechanisms away from the insole and shoe upper at a height greater than that of the top of the rib of the insole, and means operating progressively with the gripper mechanisms for inserting separate fastenings through the marginal portions of the shoe upper into the insole and last to secure the upper in lasted relation thereto.

98. A lasting machine having, in combination, a support for a last having a shoe upper and ribbed insole assembled thereon, a pair of grippers arranged to engage the upper at opposite sides of the last, operating means for imparting an impositive heightwise movement to the grippers to tension the shoe upper about the last, and means cooperating with said last-named means to cause a positive heightwise movement to be imparted to the grippers to maintain the upper limit of movement of the grippers above the top of the rib of the insole.

99. A lasting machine having, in combination, a jack arranged to carry a last having an insole and a shoe upper assembled therewith, a pair of gripper mechanisms arranged to engage the marginal portions of the shoe upper on opposite sides of the last, means for causing relative movement of the jack and the gripper mechanisms lengthwise of the last to cause the gripper mechanisms to operate progressively along the shoe upper, and means for moving the gripper mechanisms heightwise of the last to cause the gripper mechanisms to stretch the shoe upper progressively over the last arranged to maintain the limit of the movement of the gripper mechanisms away from the insole and shoe upper at a greater height than that of the top of the rib of the insole.

100. A lasting machine having an abutment arranged to engage the inner surface of the rib

of an insole positioned on a last, a gripper arranged to engage the edge of a shoe upper assembled upon the last and means for operating the gripper to grip the shoe upper and to move heightwise of the last to stretch the shoe upper over the last including a pair of springs, means for operating the springs to vary the tension with which the grippers stretch the upper, and a stop for limiting the yielding movements of the springs.

101. A lasting machine having, in combination, a jack, a gripper arranged to engage the marginal portion of a shoe upper to stretch the upper about a last carried by the jack, a lever connected to the gripper, operating means to rock the lever thereby to close the gripper upon the shoe upper and to move the gripper heightwise of the last to stretch the shoe upper over the last, a spring connected to the lever for causing relative movement between the lever and the operating means, and a stop for limiting the yielding movement of the spring.

102. A lasting machine having, in combination, a jack, a gripper arranged to engage the marginal portions of a shoe upper to stretch the upper over a last carried by the jack, a lever connected to the gripper, means operating through a spring to rock the lever to close the gripper upon the shoe upper and to move the gripper heightwise of the last to apply a yielding pull to the upper, and means for limiting the yielding movement of the spring.

103. A lasting machine having, in combination, means for pulling an upper over a last having a ribbed insole positioned thereon, a wiper movable to lay the margin of the upper inwardly against the rib of the insole, a spring operated driver movable relatively to the wiper to insert a fastening through the upper and the rib of the insole, an anvil member arranged to engage the rib and to clinch the fastening, said anvil member being mounted for movement about an axis in response to the pressure of the wiper, a spring against the resistance of which said member is thus movable, and means carried by the wiper for limiting the operative movement of the driver.

104. A lasting machine having, in combination, means for tensioning an upper over a last having a ribbed insole positioned thereon, a wiper for laying the tensioned margin of the upper inwardly against the rib of the insole, a driver for inserting a fastening through the upper and the rib of the insole, a pivotally mounted anvil arranged to engage the rib of the insole and to clinch the fastening, a stop, a spring for holding the anvil in engagement with the stop, and an abutment carried by the wiper for limiting movement of the driver toward the anvil.

ROBERT H. LAWSON.
